22 SHEETS—SHEET 12.

This technical cross-sectional diagram illustrates a complex mechanical assembly, possibly a pump or valve mechanism. The drawing is oriented vertically, showing two main sections of the machine. Key components include:

- Top Section:** Features a vertical cylinder or piston assembly with a rod (98) extending downwards. A lever system is attached to the rod, with a connecting rod (28) and a crank (34) at the bottom. A valve or piston (102) is shown in the middle section. Various valves and ports are labeled with numbers such as 99, 101, 102, 97, 93, 84, 82, 20, 28, 41, 35, 34, 30, 180, 273, 194, 196, 36, 32, 30, 33, 34, 35, 36, 179, 193, 192, 196, 38, 39, 50, and 51.
- Bottom Section:** Shows a horizontal cylinder or piston assembly with a rod (20) extending upwards. A lever system is attached to the rod, with a connecting rod (27) and a crank (23) at the top. A valve or piston (81) is shown in the middle section. Various valves and ports are labeled with numbers such as 23, 20, 27, 44, 45, 46, 47, 48, 35, 34, 30, 179, 193, 192, 196, 38, 39, 50, and 51.

The diagram uses hatching and cross-hatching to differentiate between different parts and materials within the assembly. The entire drawing is enclosed in a rectangular border.

UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

MACHINE FOR FEEDING SHEETS.

SPECIFICATION forming part of Letters Patent No. 768,375, dated August 23, 1904.

Application filed June 6, 1903. Serial No. 160,331. (No model.)

To all whom it may concern:

Be it known that I, HOWARD K. KING, a citizen of the United States, residing at Philadelphia, in the county of Philadelphia and State of Pennsylvania, have invented a new and useful Machine for Feeding Sheets, of which the following is a specification.

My invention relates to feeding-machines, and is more especially intended for use in connection with sheet-feeders in which individual sheets are separated from a pile or bank of sheets and delivered to a receiving device, my object being to provide improved means for automatically feeding the sheets one at a time and each at the precise moment that the receiving mechanism is ready to receive it.

My invention comprises improved means for coupling the operations of the feeding and receiving mechanisms so that both will act in unison.

My invention also comprises improved combing means for combing the sheets forwardly one in advance of the other and automatic means actuated by the advancing sheet for controlling the action of the combing means, said automatic means being pneumatically operated.

My invention also comprises improved means for storing air and regulating the pressure thereof.

My invention also comprises improved valve mechanism for controlling the pneumatic means.

My invention also comprises improved means for blowing air between the sheets to assist in their separation.

My invention also comprises improved guiding and pressing means for maintaining the position of the pile and for coöoperating in the separation of the sheets therefrom.

My invention also comprises improved automatic means controlled by the pile of sheets for maintaining the top of the pile of sheets at the proper elevation.

My invention also comprises improvements in details of construction.

Referring to the accompanying drawings, Figure 1 is a plan view of my device. Fig.

2 is a side elevation. Fig. 3 is a rear elevation. Fig. 4 is a vertical section on lines 4-4 of Fig. 1. Fig. 5 is a vertical section on lines 5-5 of Fig. 1. Fig. 6 is a detail of the valve-trip mechanism in a different position from that shown in Fig. 5. Fig. 7 is a partial front elevation omitting the upper structure. Fig. 8 is a sectional view on lines 8-8 of Fig. 7. Fig. 9 is a partial plan view of the mechanism shown in Fig. 7. Fig. 10 is a partial front elevation and partial section on lines 10-10 of Fig. 14. Fig. 11 is a vertical section on lines 11-11 of Fig. 10. Fig. 12 is a vertical section on lines 12-12 of Fig. 10. Fig. 13 is a vertical section on lines 13-13 of Fig. 10, but showing the head on the opposite side of the machine having the shaft 98 journaled in it. Fig. 14 is a vertical section on lines 13-14 of Fig. 10, the scale being somewhat reduced. Fig. 15 is a detail of a portion of the rod supporting the combing-wheel. Fig. 16 is a detail in elevation of manually-operative means for raising the combing-wheel, showing the combing-wheel indicated as raised. Fig. 17 is a front view of same. Fig. 18 is a similar view to Fig. 16, the combing-wheel indicated as lowered. Fig. 19 is a plan view of the operating-head shown in Fig. 13. Fig. 19^a is a detail showing section of rod 23 and portion of member 80. Fig. 20 is a diagrammatic plan view showing means for operating the combing-wheel on the edge of the sheet. Fig. 21 is a detail of one of the presser-weights as shown in Fig. 20. Fig. 22 is another detail of one of the presser-weights and guide as shown in Fig. 20. Fig. 23 is a detail in rear elevation showing the presser-feet and associated mechanism. Fig. 24 is a plan view of the drop-roller and associated mechanism and a cross-section of the combing-wheel on line 24-24 of Fig. 5. Fig. 24^a is a cross-section on the line *a-a* of Fig. 24. Fig. 24^b is a cross-section on the line *b-b* of Fig. 24. Fig. 25 is an elevation, partly in section, of a combing-wheel. Fig. 26 is a cross-section on line 26-26 of Fig. 25. Fig. 27 is a longitudinal section on lines 27-27 of Fig. 28 of the clutch-gear mechanism for operating the

screws for elevating the table. Fig. 28 is a cross-section of same on lines 28 28 of Fig. 27. Fig. 29 is an elevation in detail of the mechanism for controlling the height of the pile of sheets. Fig. 30 is a partial elevation of same, showing the mechanism in a different position. Fig. 31 is a plan view of the pawl mechanism, showing means for arbitrarily throwing the same out of operative position. Fig. 32 is a section on lines 32 32 of Fig. 31. Fig. 33 is a side elevation of Fig. 31, showing the pawl in inoperative position. Fig. 34 is a similar view showing the mechanism in the operative position. Fig. 35 is a side elevation of detail 15 of latching means for controlling the operation of the drop feed-roller. Fig. 36 is a similar view showing the mechanism in a different position. Fig. 37 is a similar view showing the mechanism in a different position. Fig. 37^a is an enlargement of a portion of Fig. 37 in a slightly different position. Fig. 38 is a side elevation of cut-off air-valve to be operated when the combing-wheel is arbitrarily raised. Fig. 39 is a section on lines 39 39 of Fig. 38. Fig. 40 is a detail rear elevation, partly in section, showing presser-foot guide and blowpipe. Fig. 41 is a cross-section on lines 41 41 of Figs. 40 and 42, showing the presser-foot and the blowpipe in elevation. Fig. 42 is a plan view of the presser-foot mechanism. Fig. 43 is a cross-section on lines 43 43 of Fig. 42, the section being slightly enlarged. Fig. 44 is a detail in elevation of the presser-weights. Fig. 45 is a vertical cross-section on lines 45 45 of Fig. 44. Fig. 46 is a horizontal section on lines 46 46 of Fig. 44. Fig. 47 is a side elevation of one of the side blow-pipes, showing the same inclined. Fig. 48 is a rear elevation of 40 a similar pipe in the vertical position. Fig. 49 is a rear elevation of the rack-and-pinion means for moving the table. Fig. 50 is a cross-section on lines 50 50 of Fig. 49. Fig. 50^a is a plan view of a hand-lever for coöperating with the square end of shaft 244. Fig. 51 is a horizontal section on lines 51 51 of Fig. 49. Fig. 52 is a plan view of a portion of the feed-table and a part section on lines 52 52 of Fig. 53. Fig. 53 is a vertical section on lines 53 53 of Fig. 52. Fig. 54 is a vertical section on lines 54 54 of Fig. 52. Fig. 55 is a rear elevation of the air-reservoir and automatic pressure-regulator. Fig. 56 is a vertical section on lines 56 56 of Fig. 55, showing the lever in elevation. Fig. 57 is a cross-section on lines 57 57 of Fig. 9. (See Sheet 6.) Fig. 58 is a cross-section on lines 58 58 of Fig. 52. (See Sheet 20.) Fig. 59 is a section on lines 59 59 of Fig. 7. 50 Similar numerals refer to similar parts throughout the several views.

Referring to Figs. 1, 2, 3, 4, 5, 13, and 14, the sheets 2 to be fed are placed upon the table or platform 1, set at the proper elevation, so that the top sheet will readily pass

between the guide members 3 and 4. The combing-wheels 5 are then rotated over the top sheet in the manner hereinafter explained to comb the sheet through the guide members toward the receiving mechanism, to which belong the feed-roller 6 and the drop-roller 7—that is, the first forward movement of the sheets is caused by the combing-wheels 5. While the drawings show a machine using two combing-wheels, I can use one or more of 70 said combing-wheels, depending upon the size or other characteristics of the sheets to be operated on. As these combing-wheels and much of the operative mechanism connected therewith are substantially in duplicate, it 75 will be sufficient to describe a single wheel and its associated mechanism, as follows:

Combing-wheel, means for raising and lowering the combing-wheel.—The combing-wheel 5 rests upon the pile of sheets 2 and is rotated 80 in the direction of the arrow shown in Figs. 4 and 5 to comb the sheets forward, whereby the sheets are moved forward between the guides 3 and 4, the top sheet in advance of the under ones, until the top sheet encounters 85 the valve-trip 8, which is pivoted at 9 and controlled by the spring 10. This valve-trip 8 has a projecting member 11, (best shown in Fig. 13,) which is adapted to engage the lower end of valve-piston member 12 and normally hold the same in the elevated position, as 90 shown in Fig. 14. When the trip is actuated by the advancing sheet, the member 11 is depressed to allow the descent of valve-piston 12, as shown in Fig. 13—that is, the piston falls of its own weight—whereupon communication is opened with the air-pressure from tube 13 into the diaphragm-chamber 14 to cause the upward movement of the diaphragm 15 and piston 16 and rod 17, carried thereby. 95 The upper end of piston-rod 17 encounters the free end of member 18, which is integral with lever 19 and rigid with shaft 20, which rotates in brackets 21 and 22. The free end of lever member 19 is pivotally connected 100 with the connecting-rod 23, the lower end of which is pivotally connected with the stud 24, rigidly secured to the rocking frame 25. Upon this stud 24 rotates the combing-wheel 5. The upward movement of members 18 105 and 19 through the connecting-rod 23 causes the lifting of the combing-wheel 5 from engagement with the paper 2. For purposes of convenience and construction the outer end of member 18 is provided with a toe-piece 26, 110 of hardened metal, for engagement with the upper end of piston-rod 17.

Operating means for presser-foot.—Refer to Figs. 4, 5, 10, 13, 14, 19, 23, and 29. To shaft 20 is also rigidly secured the arm 27, 115 provided at its free end with a sector-gear 28, which meshes with the coöperating gear 29 of the lever or arm 30, which is loosely mounted on the hub 31, which is rigid with the shaft 32. From hub 31 extends the arm 33, which 120

is provided with the stud 34, to which is secured the spring 35, the other end of which spring is secured to the stud 36 on the member 30. This spring 35 serves normally to hold the face 37 of arm 33 against the stud 36 of member 30. Upon the rotation of shaft 20, as above described, movement is communicated, through arm 27 and gears 28 and 29, to arm 30. By the movement of the arm 30 in the direction of the arrow shown in Fig. 23 motion is communicated, through the spring 35, to the arm 33, which is rigidly secured to shaft 32, whereby shaft 32 is rotated to cause the movement of arm 38 and presser-foot 39 to clamp the pile of sheets at the rear of the top sheet, which has just cleared the presser-foot. The spring connection between members 30 and 33 permits of further movement of shaft 20 after the presser-foot 39 has reached the limit of its movement. This obviously results in a spring-pressure being exerted by the presser-foot 39 on the pile of sheets—that is, the adjustment of the connecting mechanism between the rotating shaft 20 and the stud 24, carrying the combing-wheel 5, and the shaft 32, carrying the presser-foot 39, is such that the presser-foot comes in contact with the sheets before the full upward movement of the combing-wheel. The limit of the upward movement of piston 16 and the consequent movement of shaft 20 and the upward movement of the combing-wheel is secured by the engagement of the upper part of piston member 16 with the shoulders 40 of the surrounding walls of chamber 14.

The arrangement just described, and shown in Figs. 4 and 23, is the construction connected with the shaft 32 on the left-hand side of the machine. The operation with respect to shaft 32 on the right-hand side of the machine is the same to and including member 33 with this addition. Referring to Figs. 5, 19, 23, and 29, I show hub 31 provided with the arm 41, said arm 41 being similar to arm 33, with the exception that it has an extension above the line connecting studs 34 and 36. The operation between 30 and 41 is similar to that between 30 and 33. The upper extremity of member 41 is provided with a latch-piece 42 for controlling the mechanism for elevating the pile of sheets hereinafter to be described.

Upon shaft 20 is rigidly secured the arm 43, at its free end provided with a set-screw 44, which is adapted to impinge the free end of arm 45, mounted on the rock-shaft 46 and rotatably fixed therewith. Rigidly secured to shaft 46 is the latch-arm 47, which is normally controlled by the spring 48 for controlling the movement of the roller 49 in the following manner:

Drop-roller control.—The roller 49 is an idler mounted in the upper guide-frame 3, which is mounted on shaft 50, so as to have a rotative movement therewith. Rigidly secured to shaft 50 is the cam-arm 51, being

normally controlled by the spring 52, so as to engage with the periphery of the cam-wheel 53, an antifriction-roller 54 being secured to arm 51 for this purpose. Referring to Figs. 4, 23, 35, 36, and 37, the outer free end of member 51 is provided with the steel piece 55, which is adapted to engage with the steel piece 56, which is connected at the outer extremity of arm 47. The latching member 56 (see Fig. 4) is pivotally secured to the arm 47 at 75 57 and is normally controlled by spring 58, so that it may yield to permit of movement of member 45 in case there should be any necessity for the downward movement of member 45 when the members 55 and 56 are in the 80 relative positions shown in Fig. 36. In the position shown in Figs. 4, 13, and 14 the idler 49 is maintained above and out of contact with the roller 59, which is constantly rotating. When the idler 49 is depressed or descends to press the sheets against roller 59, as shown in Fig. 5, the sheets are transported therebetween. In order that the sheets may be delivered to the receiving device, such as a folding-machine, at the proper moment to 90 coincide with the operation of the receiving device, the mechanism above referred to operates as follows: In connection, for example, with such a receiving-machine as a folder in which a feed and drop roller mechanism is 95 employed I provide the cam-wheel 53, which is driven by and in unison with the folding-machine. This wheel is provided with the depression 60 and is adapted to make a revolution with each complete operation of the feed and 100 drop roller mechanism of the folding-machine, which results as follows: When the advancing sheet has operated the valve-trip 8, resulting in the rotative movement of shaft 20 and the consequent movement of the latch member 47, so 105 that 55 will clear 56, the sheets are ready to be fed to the folding-machine, but cannot be delivered until the cam-wheel 53 has come in such a position that the roller 54 may enter into the depression 60. This permits the descent of 110 roller 49 to cause the engagement of the sheets with the driven feed-roller 59 to carry it forward to the feed and drop roller mechanism of the folding-machine. The depression 60 in cam-wheel 53 is of such longitudinal dimension 115 as to permit the coöperation of rollers 49 and 59 only so long as is necessary to carry the sheet into engagement with the feed and drop roller mechanism of the folding-machine, whereupon the continuing rotation of cam-wheel 53 120 after the limit of the depression 60 has been reached causes the movement of 51 back to normal position against the spring 52 and the resulting upward movement of roller 49 out of engagement with roller 59. It is to be 125 noted, however, that member 51 will not be permitted to respond to the depression in the cam-wheel 53 unless the latching member 47 has been actuated, as above described, as a result of the paper reaching the proper position 130

in the feed device. It is also to be noted, as above stated, the depression 60 in cam-wheel 53 is of such longitudinal dimension as to permit the coöperation of rollers 49 and 59 only 5 so long as is necessary to carry the sheet into engagement with the feed and drop roller mechanism of the folding-machine, whereupon the continuing movement of the cam-wheel 53, after the limit of the depression has been 10 reached, causes the movement of 59 back to normal position. From this it follows that in case 54, by reason of delay in the elevation of the combing-wheels because of tardy combing or other reason, should not be permitted 15 to enter depression 60 at the very commencement thereof it would fail to have the benefit of the full longitudinal dimension of said depression 60, which is required to permit member 51 to be maintained in such position to hold 20 the drop-roller in the operative position a sufficient space of time to complete the feeding of the sheet. It is therefore necessary that roller 54 must not be permitted to enter depression 60 except at the very commencement 25 thereof. I have therefore constructed the co-operating faces of 55 and 56 as follows: Referring to Fig. 37^a, the upper or contacting face 295 of 55 is slightly beveled or indented to coöperate with the corresponding beveled 30 face 296 of 56, from which it results that when wheel or roller 54 comes into coincidence with depression 60 before 55 and 56 have been disengaged spring 52 will exert its force on 51 to cause the member 55 to press 35 firmly against the beveled coöperating surface of member 56 to prevent the member 47 responding to spring 48, even when so released by the elevation of the combing-wheel, until the depression 60 has been passed and roller 40 54 has been pushed out of same to counteract the pressure of spring 52, whereupon 56 is released in response to 48 and 51 is free to respond to the depression 60 when it is reached in the next revolution, so that the travel of 45 54 through the full extension of depression 60 is assured. It is thus positively provided that the sheet is not fed until it is assured that it will be fully fed.

It should be noted that Fig. 37 shows the 50 latch in the usual position of engagement when the sheet misses in combing in time, while Fig. 37^a shows the position of the latches as the result of the starting to unlatch at the same time that roller 54 starts into depression 60, 55 thus providing that the combing-wheels shall reach a required elevation before depression 60 reaches roller 54; otherwise the cam-wheel 53 must make another revolution while the combing-wheels are elevated before the roller 60 is permitted to enter said depression. It is also to be noted that there are two combing-wheels in the specific device shown in the drawings, one on one side and the other on the other side of the machine, two valve-trips 8, each controlling in the manner above described a dif-

ferent shaft 20. Upon shaft 46 is provided two arms 45, one controlled by one shaft 20 and the other controlled by the other shaft 20. (See Fig. 23.) It is obvious from this arrangement that it will be necessary for both valve-trips to be actuated in order to permit the actuation of shaft 46 to cause 56 to clear 55. From this it results that the sheets must be perfectly straight and square in its presentation to the folder before it can be moved by 75 the rollers 59 and 49. In case the sheet is not at first presented in such manner the part of the sheet which is lagging will continue to be operated upon by its combing-wheel until it has been brought in line. 80

The feed and drop roller mechanism used in connection with folding-machines is well known in the art and obviously need not be described in detail. It comprises a driven feed-roller and a coöperating drop-roller 85 adapted to be moved to and away from the feed-roller at desired intervals, and, as above stated, the operative connection between this mechanism and the cam-wheel 53 is such that the revolution of the cam-wheel will have a 90 certain desired ratio with the complete operation of the feed and drop roller of the receiving mechanism.

When the entire sheet has passed beneath the valve-trip 8, the trip returns to the initial position, as shown in Fig. 14, responding to actuation of spring 10, and elevates the valve-piston 12 to the initial position, which shuts off the admission of air from tube 13 and opens communication between chamber 14 and the outer air. This permits the diaphragm 15 and piston member 16 to drop to the initial position, permitting the return to the first position of shaft 20 and the various mechanisms actuated thereby, which completes the cycle. 105

Valve mechanism.—The valve mechanism operating between the compressed-air-supply tube 13 (said compressed-air supply being furnished by a pump or blower or other suitable means) and the diaphragm-chamber 14 110 is constructed and operates as follows: Referring, preferably, to Figs. 13 and 14, the piston member 12 reciprocates in the cylinder 61, which is provided with three sets of openings each 62, 63, and 64. The upward movement of the piston is limited by encountering the projecting edge 65 of the cylinder-cap. The limit of its lower movement is caused by the engagement of the lower piston 66 with the lower cylinder-plate 67. When the piston member 12 is in the position shown in Fig. 13, the air is admitted through openings 62 and 63 to the passage leading to diaphragm-chamber 14. When the valve-trip 8 is returned to the initial position, as shown in Fig. 14, thereby lifting the piston member 12 to its elevated position, the passage of air is cut off from opening 62 to opening 63, and communication is opened through 63 and 64 from diaphragm-chamber 14 to the outside atmos- 130

phere. As will be noted, the piston member 12 is provided with the three pistons so positioned as to insure an equalizing pressure of air upon said member. The stop or projection 65 to limit the upward movement of the piston member is made with a knife-edge to prevent the piston from sticking or being held up by suction. The power for operating the feeding device is derived from the gear 68, 10 which is operated in connection with the folding-machine or other receiving mechanism. Power is communicated from 68 to the gear 69, on the hub of which is mounted gear 70, which meshes with 71. 71 drives 72, and 72 15 drives 73. (See Figs. 1 and 2.) On the hub of gear 71 is 74, which drives the idler-gear 75, through which gear 76 is driven. 73 is mounted on shaft 77, upon which are mounted the gears 78, one for each combing-wheel. 20 (See Figs. 5 and 24.) These gears 78 mesh with gears 79, upon which the combing-wheels are mounted. Said gears 79, to which the combing-wheel is secured, rotates on stud 24, which is rigidly secured in frame 25, so that 25 the gear-wheels 78 and 79 are maintained in fixed relative positions as to the distance between their centers. The frames 25 are journaled in the stationary structure 80. The shaft 77 is journaled at either end in the stationary frame and also in the rotative oscillative frames 25.

Automatic table-raising mechanism, (see Figs. 2, 5, 19, 23, 29, and 30).—Shaft 81 is driven by gear 72. Near the other end of this shaft is mounted the cam 82 and crank 83. Connected with the crank 83 is the connecting-rod 84, the other end of which is pivotally connected at 85 with the rock-arm 86, which rotates loosely on shaft 87. Carried 40 at the free end of this rock-arm 86 is the pawl 88. The ratchet-wheel 89 is rigidly mounted on shaft 87. The shaft 87 is provided near each end with the beveled gears 90 and 91, which are adapted to mesh with the beveled gears 92 and 93, respectively, which are secured to the vertically-disposed screws 94. These screws 94 are supported in bearings against downward movement, but so as to permit of rotative movement. Upon these 45 vertical screws 94 are carried the brackets 95, with suitable means connected therewith for meshing with the thread of the screws. To these brackets is secured the platform 1 for holding the pile of sheets. It will now be 50 obvious that the rotation of the screws in one direction will cause the elevation of the platform, while their rotation in the other direction will cause the descent of the platform. The rotation of the shaft 81 will communicate movement to the shaft 87 and through the connecting-rod 84 to the rock-arm 86. The free end of rock-arm 86 carries the pawl 88, which coöperates with the ratchet-wheel 89, mounted upon shaft 87 normally to cause the 55 actuation thereof. The actuation of the shaft

87, which communicates movement through the beveled gears to the screws 94, will cause the elevation of the platform 1. If, however, the cam-and-pawl actuation of shaft 87 were permitted to take place upon each revolution of shaft 81, the movement of the screws, and the consequent elevation of the platform 1, would be entirely too rapid, and to prevent such continuous actuation the following mechanism is provided to permit of such actuation 75 only from time to time, depending upon the height of the pile of sheets: Mounted on shaft 81 is the cam-wheel 82, upon which presses the cam-roller 96, which is mounted upon the arm 97. Arm 97 is rigidly mounted on and rotates 80 with shaft 98. At the upper end of member 97 is pivotally secured the tripping member 99, which slides in the bracket 100. A reciprocating movement is given this member 97 and tripping member 99 by the cam-shaped peripheral surface of wheel 82, so that when the circular part of the wheel 82 is in engagement with the roller 96 the trip is held in the withdrawn position; but when the roller comes into the depressed part of cam-wheel 82 the 90 tripping member 99 is moved forward into engagement with the tripping-lug 88^a of pawl 88 to prevent its operating the ratchet-wheel 89. Rotatably fixed with the shaft 98 is mounted the arm 101, having a steel toe-piece 102, 95 which is adapted to engage with the latch-piece 42 on arm 41. Arm 41 is rigid with shaft 32, (see Figs. 5 and 23,) to which is also secured the presser-foot member 38. So long as the pile of sheets beneath the presser-foot is of 100 normal height the shaft 32 and arm 41 are held in such position that 102 will clear 42; but as soon as the pile of sheets falls below a predetermined height the shaft 32 and arm 41 assume a position in which 102 will encounter 105 42. With this construction it follows that when the pile of sheets is at normal height the arm 41 is held in such position that 42 will not encounter 102, so that the roller 96 will be permitted to drop into the depression of 110 the cam-wheel 82 and cause the forward movement of tripping member 99 to engage pawl 88 to prevent its coöperating with ratchet-wheel 89 at the forward movement of the rock member 86; but when the pile of sheets falls 115 below the normal or required height the presser-foot 39 responds thereto and permits the actuation of shaft 32 and arm 41, so that 42 will encounter 102 and prevent the movement of shaft 98. From this it results that 120 when the depressed part of the cam-wheel 82 reaches the roller 96 the said roller is prevented from moving into the same in response to the actuation of spring 103, because the shaft 98, upon which its arm is mounted, is 125 locked from rotating, as above described, by the member 101, and therefore prevents the forward movement of the tripping member 99 to encounter tripping-lug 88^a of pawl 88, thus permitting pawl 88 to actuate ratchet- 130

wheel 89 and through the connecting mechanism described causing the elevation of the table until the presser-foot 39 is sufficiently moved to cause the movement of 41 to disengage 42 from 102 and permit the reciprocation of arm 97 and tripping member 99, as above described. As a matter of fact, the movement of one tooth of the ratchet-wheel is more than sufficient to accomplish this result.

10 It is to be noted that the table may also be raised or lowered by the operation of a hand-crank 104, which is adapted to fit on the end of shaft 87 and also on the hub of gear 105, which is adapted to mesh with gear 106, which is rigid with shaft 87. (See Fig. 1.) It is obvious that the shaft 87 may thus be turned by hand in one direction—namely, the direction for raising the table—with the pawl and ratchet in normally operative position; but in order 15 to turn the shaft in the other direction—namely, to lower the table—the pawl must be moved out of engagement with the ratchet-wheel and held there, it being understood that the pawl in the structure shown in the drawings normally falls by gravity into engagement with the ratchet-wheel 89. It is obvious, however, that the pawl might be controlled by spring or other equivalent means. For this purpose I have provided the following 20 mechanism: Pawl 88 is carried on the stud 107 and has a rotative movement thereon. Also mounted on this same stud 107 is the member 108, which has a projection 109, adapted to overlap the tail of pawl 88. Secured to 25 this member 108 is the leaf-spring 110, the free end of which is adapted to overlap or press against two flattened portions 111 and 112 of the stud 107, said flattened portions being disposed approximately at right angles 30 with each other. These flattened portions are also so disposed that when member 108 is turned in one direction about the stud 107 it is so held that the projection 109 is clear from the tail of the pawl 88, as shown in Fig. 34, but 35 when the member 108 is rotated on the stud 107 in the other position it is so held by the spring engaging on the flat surface of said stud as to maintain the projection 109 in contact with the tail of pawl 88, so as to hold it 40 out of engagement with the ratchet-wheel 89, as shown in Fig. 33. In this position it is possible to rotate shaft 87 in the direction to cause the descent or lowering of the table 1. This spring lies in a peripheral groove in said 45 stud and serves the additional purpose of locking the member 108 upon said stud.

Means for stopping and starting the feeding by raising and lowering the combing-wheel.—It may be noted that the combing-wheel and feeding-wheel and other mechanisms of the feeding device are moving as long as the receiving mechanism, such as the folding-machine, is operating, and therefore it is necessary to start and stop the feeding operation without necessarily stopping all the

mechanism, or, in other words, to move the combing-wheel arbitrarily out of and into the operative position. For this purpose I have provided the following mechanism: As has already been described, when the valve-trips 5 are in initial position—that is, until they have been actuated by the advancing sheet—70 the combing-wheels are normally down—that is, pressing the sheets—or in the operative position. Referring to Figs. 16, 17, 18, and 19, 75 it has been explained that the combing-wheel 5 was automatically raised and lowered through the actuation of arms 18 and 19, rotating with shaft 20. Integral with arms 18 and 19 on the other side of the supporting-shaft 20 is a projection provided with the roller 113. Suitably supported in the stationary framework of the machine is the shaft 114, having a rotative movement in said supports. Adjustably secured to this shaft 114, but rotatably rigid therewith, is the cam member 115. This member is so placed as to have engagement with the roller 113. Rigidly secured to the shaft 114 is the arm 116, to the free end of which is attached the handle or rod 117, which is slidably supported in the guide 118. The extent of reciprocative movement of rod 117 is secured by the collars 119 and 120, located on said rod on either side of the fixed guide 118. (See Fig. 2.) It is now 80 obvious that by the reciprocation of this rod 117 a consequent rotative movement is communicated through arm 116 to shaft 114, which results in the operation of the cam 115 against roller 113 to cause the rotative movement of members 18 and 19 in one direction to lift the combing-wheel and in the other direction to permit the rotative movement of members 18 and 19 to lower the combing-wheel. The slight depression 306 is provided in the cam 85 member 115 to coöperate with the roller 113 to hold member 115 in engagement with roller 113 when the combing-wheels are elevated. It is therefore obvious that by this mechanism the operator may arbitrarily move the 90 combing-wheel into and out of engagement with the paper whenever it may be desirable.

Air cut-off.—When, however, the combing-wheel is arbitrarily, that is, raised by hand from the pile of sheets, it is also desirable to 95 cut off the air-current which is being directed into and between the sides and rear of the pile of sheets, or otherwise too much air would be blown between the sheets. For this purpose I have located at a convenient point in the supply-pipe 130 the rotating slide-valve 131, 100 inclosed in the chamber 132 and lying against the flat face of the wall 133 of said chamber, said wall being provided with the aperture 134, which corresponds with the opening of pipe 105 135.

Air-supply for the purpose of operating the diaphragm and piston above referred to and also for air-blasts for the sheets is furnished in the specific device illustrated in Fig. 2 of 110 130 135

the drawings by the rotary blower 136. Said blower being a well-known device in the art, it is not thought necessary to describe the same.

Reservoir and pressure-regulator.—The supply of air furnished by the blower is above the various requirements of the machine. Said quantity and pressure of air furnished by the blower is regulated by the mechanism shown in Figs. 55 and 56, in which 137 represents a reservoir. This reservoir is connected by pipe 171 to the distributing-pipe 130, leading from the blower 136. (See Fig. 2.) At one side of this reservoir is provided a flexible diaphragm 138, which is secured or clamped to the walls of the reservoir by the head 172. To the outside of this diaphragm is secured the piston 139 and rod 140. Piston-rod 140 is pivotally secured at its outer end to the lever 141, which is pivoted at one end at 142 to the framework of the chamber 137. To the free end of lever 141 is secured the spring 143, which is secured at the other end to the rod 144, this rod being adjustable through a projection 145 by the thumb-nut 146 coöperating with the thread on said rod. Adjacent the flexible wall 138 of the chamber 137 is the cylindrical vent 147, in which is seated the valve 148, having a joint with the outer edge of said cylinder, said valve being yoked around the lever 141 and normally held in the closed position by said lever under the control of the tension-spring 143—that is, the spring adjustment and proportion of arm 140 and the area of flexible diaphragm 138 are such as to maintain the required pressure in chamber 137—that is, the valve 148 is controlled so that it will permit the escape of air beyond the required or normal pressure in chamber 137—that is, the required pressure to be maintained in 137 is secured by the adjustment of spring 143. It is obvious since this reservoir is in communication with the distributing system of compressed air it will serve to maintain a uniform pressure of air in said system, and also since it has a considerable cubical capacity it will serve as an air-cushion to neutralize the vibrations due to the blower or pump.

Air distribution.—The distribution of air from the blower 136 is as follows, (see Figs. 1 and 3:) through pipe 130 to the cut-off valve 131 in casing 133, to pipe 135, which crosses the top of the machine, and from which are led branches 149 and 150, leading to the diaphragm-chamber 14, through pipe 151, controlled by valve 304, to branches 152 and 153, leading to two rear blowpipes 154 and 155 and through valves 302 and 303 to 156 and 157, leading to side blowpipes 158 and 159. The valves 302, 303, and 304 are manually operative for controlling the supply of air to the blowpipes. The valve member 131 is journaled in the casing 133. (See Figs. 38 and 39.) Journaled in the opposite wall 161 is the crank member 162, having a finger 163 at its free end resting between the two pro-

jections 164 of the valve member 131. This crank member 162 is provided with the collar 165, adapted to bear against the walls of member 161 to secure a tight air-joint and to prevent movement in the direction away from the valve member 131. To crank member 163 is secured the arm 166, which is linked by member 167 to arm 168, which is rigidly secured to shaft 114, whereby it is obvious that upon the rotation of shaft 114 will result the rotation of crank member 162 and the consequent movement from the closed to the open position, and vice versa, of valve member 131. Centrally seated between the crank member 162 and valve member 131 is the spring 160 to cause the air-tight engagement of valve member 131 against the smooth face of member 133 and also to increase the efficiency of engagement and consequent air-tight joint between crank member 162 and member 161. Referring to Fig. 38, the arms are shown in a position in which the valve member is closed. It is also to be noted that the pivotal connection between the member 167 and 168 is a slot-and-pin connection—that is, the slot in the member 168 is open at one side—so that when for any reason it is desirable to arbitrarily open the valve when the shaft 114 is in the closed position or in the position which would hold the valve closed the member 167 may be lifted by hand out of engagement with the pin 170 and pushed in the direction indicated by the arrow.

Means for blowing air between the sheets.—For the purpose of separating and loosening the sheets from each other during the combing process air is blown between the upper layer of sheets at each side about the center of the pile and also to the rear of the sheets, preferably back of each combing-wheel. The side blowpipes 158 and 159 are shown in Figs. 3 and 4 and are provided with shields 173 and 174 to limit the upward movement of the sheets in response to said air-current and to prevent the upper sheets from being lifted beyond the influence of the current. The efficiency of this loosening up or separating of the upper sheets one from the other is greatly increased by the air-blasts in the rear. These are directed against the edges of the sheets, which are combed one in advance of the other. These blasts are directed in a slightly downward or slanting course, striking the top portions of the sheets and acting with great efficiency against each individual edge of the sheet in advance. For instance, where, as with the side blasts, the current is directed against the straight or perpendicular side of the pile or sheets the current seeks the course of least resistance and where two or more sheets may stick together the current is liable to pass only through or between the sheets more readily separated, whereas with the coöperation of the rear blasts above described the positive

separation of each sheet is assured. In this way the sheets are loosened up and made to move one away from the other by the action of the combing-wheel without tendency to stick or move together. This results in a uniform combing of the paper, so that the spacing between the advancing edges of the sheets by the combing action is maintained regular and uniform. The adjustment of these various blowpipes is provided for as follows: The side blowpipes 158 and 159 are slidably secured to the horizontal rods 175 and 176 and are vertically adjustable in the loop at the end of said rods, being secured thereto by the thumb-nut 177, such as is shown in detail in Figs. 40 and 41. The horizontal rods 175 and 176 have a rotative and longitudinal adjustment in a clip similar to 178, (shown in Fig. 44,) which secures them to shafts 179 and 180, supported by the framework which carries the combing-wheels. The rear blast-pipes are similarly supported, so as to have vertical, longitudinal, and rotative adjustment, as shown in Figs. 40 and 41. Fig. 40 shows the blast-pipe secured by the clip 181 and thumb-nut 177 to the rod 182. It is to be noted that this blowpipe 155 is adapted to have a longitudinal adjustment and also a rotatable adjustment in the clip 181; and the clip is also adapted to rotate with respect to the rod 182, so that the nozzle of said pipe can readily be brought to any desired position to direct the current in any desired direction. The rod 182 is adjustably secured to the member 183, which is adjustably secured to the rod 184, which is supported by the stationary framework of the machine.

Pressure-weight.—For the further regulating of the combing process I provide two weights 185 and 186, as shown in Figs. 44, 45, and 46. These weights are vertically slidable on the downwardly-extending arms 187 and 188 of the member 189. This member is adjustably secured by the clip 178 to the cross-rod 184. These weights are preferably positioned in tandem—that is, in line with the direction of the movement of the sheets—and when two combing-wheels are used are positioned so as to act upon the middle of the rear portions of the pile of sheets. These weights are freely slidable on their guide-rods and are adapted to exert their entire weight upon the sheets. The forward weight 185 is adapted to rest on the rear part of the top sheet, while the rear weight 186 is adapted to rest upon the pile a few sheets back of the top sheet, as shown in Fig. 44. The purpose of weight 185 is to steady the top sheet and keep it from being pushed back by the springs of the tripping mechanism, and the purpose of the rear weight 186 is for limiting the effect of the air-blast and for retarding the combing effect upon the sheets back of those that have cleared it, so that the

combing of the upper sheets may be freer. In addition to this the combined effect of the two weights being directly in the line of the movement of the paper and in the middle part of the paper has a tendency to keep the paper moving in straight line. The weight 186 is provided with a shoulder 190, adapted to support a slide-weight 191, which is provided with a slot 192, which is of sufficient dimension only to admit the rod 188, but having an interior circular opening sufficient to admit the top of weight 186, so that when the slide-weight is slipped over the rod 188 and dropped down over the weight 186 it is securely locked into position. A number of weights 191 may be provided of different dimensions for varying the pressure of 186 upon the pile. This results in regulating the speed of combing and also the distance which one sheet is advanced beyond another.

Device for indicating proper level of pile of sheets.—Referring to Figs. 14, 15, 19, and 19^a, it will be noted that I have provided on rod 23 the notches 121, 122, and 123. A lip 124 projects from the peripheral margin of member 80 directly beside the rod 23 and so that the positions of one or more of the notches 121, 122, and 123 may be compared with relation thereto—that is to say, the middle notch when in line with the upper surface of the lip 124, as shown in Fig. 15, for instance, indicates that the combing-wheel is in normally operative position. The notches above and below said middle notch 122 indicate the range of movement permissible for said combing-wheel without passing from the operative position. It is therefore possible by the indication given by these notches to so adjust the table that the pile of sheets will be at the elevation required to make the combing-wheel operative.

Means for arbitrarily raising or lowering one side of the table independently of the other side.—In case for any reason one side of the pile should be higher or thicker than the other side in order to make both combing-wheels operative it may at times be desirable to raise or depress one side of the table independently of the other.

Referring to Figs. 27 and 28, it has been shown that shaft 87 is provided near each end with bevel-gears 90 and 91. These gears are adapted to coöperate with bevel-gears rotatably rigid with the vertical screws 94. Gear 91 is normally rigid with shaft 87, but is adapted to be disengaged from said rigid engagement with said shaft 87, so that the shaft may rotate independently of said gear 91. This is accomplished by the following mechanism: Adjacent to gear 91 is the collar 125, rigidly keyed to shaft 87. Located in this collar 125 is the latch-pin 126, provided with a head 128 for manual operation. This pin 126 is controlled by spring 127. Provided in the coöperating face of the gear member 91

is a counter-recess 129, adapted to receive the end of the spring-pressed latch-pin 127 to secure the locking of gear member 91 with the collar 125, and consequently with the shaft 87.

5 It is therefore obvious that when it is desired to lower or raise one side of the table independently of the other it is simply necessary to withdraw latch-pin 127 from the recess 129 in gear 91, so that the shaft 87 can be rotated 10 independently of said gear 91, causing the rotation of gear 92 only and its coöperating screw-gear at the other side of the table. In order that the table may be raised unevenly—that is, one side independently of the other—15 as above described, it is obvious that the nuts which coöperate with the threaded shafts 94 should not be affected by this tilting movement, since it would result in causing the thread between the nut and shaft to bind.

20 To obviate this objection, I provide the following mechanism: Referring to Figs. 52 to 54 and 58, inclusive, the nut 250 is adapted to coöperate with the vertical threaded shaft 94. Said nut carries the bracket 95. This nut is circular in its upper extension. Near the base of the circular portion are provided the two lateral projections 251. At the lower extension of the nut is provided the rectangular flange. On the upper side of this flange are the oppositely-disposed ribs 252. Over this nut the bracket 95 fits, the aperture of the bracket being circular and of such dimensions as to fit about the projections 251, so as to prevent lateral motion of the bracket on the nut. This bracket 95 rests 30 upon the oppositely-disposed ribs 252 and is provided with two flanges extending downwardly and embracing the sides of the rectangular portion of the nut, as shown in Figs. 52, 54, and 58. By reason of the close fit of 35 the surrounding bracket and the projections 251 in one direction and the space between said bracket and the round portion of the nut to permit of slight play and the fit between the flanges 252 and the base of the nut in the 40 other direction lateral movement between the bracket 95 and nut 252 is prevented, while the tilting movement of the bracket on the rib projections 252 is permitted independently of the nut, so that such table may have a slight 45 50 55 60 65 70 75 80 85 90 95 100 105 110 115 120 125 130

5c tilting position without causing the nut to bind upon the screw-shaft. The general upward and downward movement of the table is guided by the following means: The brackets 95 are provided with the two shoulders 277, which engage with the coöperating faces 278 of the hollow column, as shown in Fig. 52. This, it will be noted, prevents any lateral motion of the table with respect to the fixed or stationary framework of the machine, at the 60 same time does not interfere with the tilting movement of the table. Referring to Fig. 52, other faces, 279, at right angles with the faces or shoulders 277, are adapted to bear against the faces 280 of the stationary column to prevent lateral movement in the other direction;

but the positions of the faces 279 are approximately on a horizontal level with the nut and of such limited dimension as not to interfere with the tilting movement of the table, as above described.

Presser-foot.—The presser-foot which has been referred to above may be described, with its associated mechanism, as follows: As above described, member 38, Figs. 40 and 41, is rotatably rigid, but slidably adjustable on the rock-shaft 32 (the operation of which has been fully described) to cause the automatic lowering and elevating of the presser-foot. The member 38 has a split boss and a hand-screw 193 for clamping the same with the rock-shaft 80 32. At the free end of 38 is pivoted the member 194, and through the free end of member 194 is adjustably secured the presser-foot 39, adapted to be raised or lowered by the manipulation of the clamp-nuts 195 and 196. One of the purposes of the vertical adjustment of the presser-foot is as follows: It has been described above that one of the presser-feet is connected with mechanism for maintaining the required or predetermined height of the pile of sheets and by the vertical adjustment of this foot may be varied said predetermined height. The adjustment of the other presser-foot is simply to have it exert equal pressure and work in harmony with the first.

In view of the fact that the raising and lowering of the presser-foot is caused by the rotative movement of arm 38 if the presser-foot were rigid with said arm there would result a slight rubbing contact, which would result in a combing action which would tend to cause a side movement of the top of the pile of sheets. To overcome this objection, the intermediate member 194 is pivotally secured to member 38 and has a gravity-controlled limited free pivotal movement on said pivot 273 to neutralize this rotative movement. The limit of the pivotal movement of 194 with respect to 38 is provided as follows: 194 is pivotally secured to the bifurcated end of member 38 by the pin 273 and is provided with the shoulder 274, which is slightly spaced from the shoulder 275, provided on member 38, so that the slight space between these shoulders permits of a limited rotative movement of 194 with respect to 38. It is to be noted that arm 194 projects in substantially a horizontal direction from the bifurcated end of 38, while the lower part of presser-foot member 39 lies in substantially a horizontal position and parallel with arm 194. The contact-toe is, however, at the rear end thereof and to the rear of the free end of arm 194. By the terms "rear" and "rear end" as used in this connection both in the specification and claims is meant that end or side of the said members under which the paper passes last as it travels toward the drop and feed rollers.

An additional means for steadyng and

keeping true the sheets that have been floated by the air-blasts are the side rear guides 214 and 215, as hereinafter to be explained.

Drop-roller mechanism.—As above stated, 5 the drop-roller 49 is adapted to be raised and lowered automatically to coöperate with the feed-roller 59. This wheel 49 is mounted rigidly on shaft 49^a, Fig. 24, which shaft is freely rotatable in the guide-frame 3. This frame 10 is loosely mounted on shaft 50. Between the bifurcated portions of member 3 is secured on shaft 50 the boss 197, rotatably rigid with said shaft, but laterally adjustable thereon—that is, the boss 197 is so keyed to the shaft 15 as to prevent rotation thereon, but to permit lateral movement thereon when member 3 is moved laterally on the shaft 50 by the movement of the bracket 198, which is bolted to the framework 80. (See Figs. 13 and 24.) 20 Member 3 is coupled to 198 by the member 199, which is rigidly secured at one end to 198 and provided at its other end with the head 200. A portion of the periphery of head 200 projects into the recesses 201 of member 3 to prevent 25 independent lateral movement between members 3 and 198 and at the same time to permit independent rotative movement therebetween. To the boss 197 is secured by the screw 203 the spring 202, which may be a 30 single blade or a plurality of blades. The other end of said spring being bifurcated terminates in two converging fingers, which are adapted to embrace the screw 204 and lie between the two shoulders 205. The projection 206 of the 35 boss is so positioned as to encounter the spring 202 when the same is screwed into position and puts the spring under tension. It consequently results that the spring 202 maintains member 3 and roller 49 in the elevated position, 40 as shown in Fig. 13. Upon the descent of roller 49 to the position shown in Fig. 5 by the operation of the mechanism already described the roller 49 is brought in contact with the feed-roller 59, and the further rotation of shaft 50 serves to withdraw the projection 206 from contact with spring 202 to permit the spring to act upon the lower collar 205 of screw 204 and cause roller 49 to exert a spring-pressure. It is obvious that by turning 45 the screw 204 to raise or lower the same the desired adjustment of the roller 49 is secured.

Feed-roller.—The construction of the feed-roller is as follows: Referring to Figs. 10 and 55 13, the feed-roller is a hollow roller or drum 59, surrounding the member 207, which is rotatably fixed with the shaft 208, which is driven by gear 76. (See Fig. 2.) The inner member 207 is provided with two annular 60 grooves 209, in which are seated antifriction-balls to coöperate between members 207 and 59. Between these two annular grooves 209 in member 207 are provided a series of peripherally - located cam - pockets 210. Seated in these recesses are the balls 211. Said

recesses are so proportioned that the space between said recesses and the surrounding roller 59, as shown in Fig. 12, is greater at one part and less at the other part than the diameter of the ball seated therein, the result 70 being that when the shaft 208 is rotated in the direction of the arrow in Fig. 12 the balls 211 will be carried to the restricted space between members 207 and 59 and cause a locking engagement therebetween, which will result in the rotating of the roller 59 by the rotation of shaft 208 in the direction indicated by the arrow. When, however, the roller 59 should be caused to rotate faster than the shaft, the balls will be carried to the deeper 80 portion of the recesses, so that the same will release the engagement between 59 and 207 and the roller 49 will be free to rotate independently of the shaft 208, said rotation being upon the antifriction-balls seated in the 85 annular grooves 209 of member 207. The purpose of providing for this rotation of member 59 independent of the shaft 208 is to permit the sheet being withdrawn between the drop-roller and the feed-roller 59 at a faster 90 rate than said rollers are driven by the shaft 208, said faster rate being communicated to the sheet by the receiving mechanism indicated by the rollers 6 and 7. (See Figs. 4 and 5.) The relative position of roller 59 and 95 member 207 is maintained by abutting sides of guide member 4, in which said roller is seated, said guide member being movably supported on shaft 264 and adjustably secured thereto by the set-screw 265. (See Figs. 4, 5, 100 10, 13, and 14.)

Valve-trip mechanism.—In order that the operation of the valve-trip by the advancing sheet shall be thoroughly efficient, I prefer the following construction: Referring to Fig. 10, valve-trip 8 includes a horizontal portion with two downwardly-extending members 212 and 213. Each of these two members terminates in two broad fingers, which project into grooves in the top of guide member 4. The result is that the sheet that is fed along the top of guide member 4 must encounter the fingers of valve-trip 8 slightly above their lower extension, so that the sheet must of necessity push said valve-trip forward before it 110 can pass under the same. It is also to be noted that the upper guide member 3 is provided with four guiding-ribs, two on either side and one on each side of the downwardly-projecting members 212 and 213, which guides 115 the sheet very securely to prevent it from buckling as its front edge encounters said trip-valve 8.

Guides.—For the purpose of enabling the operator to properly place the pile of sheets 120 upon the table to be fed I provide a series of front piling-guides 216. These guides extend vertically above the front of the table, and the sheets are piled upon the table with their front edge against these guides. I also pro- 125 130

vide the side piling-guide 217, which is located at one side of the table near the front part. This guide, with the front guides, makes it possible for the operator to pile the sheets upon the table in substantially uniform position.

As shown in Figs. 8, 13, and 59, the front piling-guides 216 are bent forwardly at their upper extension into a horizontal position.

10 The horizontal extensions 285 serve as feed-guides. Said guides are adjusted so that the upper surface of their horizontal portions are in the same plane with the top surface of the feed-roller 59, and thus serve as horizontal 15 guide and support for the advancing sheet.

In Figs. 8 and 59 I show additional horizontal feed-guides for coöperating with the horizontal portion of guide 216. Each of these consists of the member 286, provided with the 20 clamping member 287 and bolt 288 for securing said member to the shaft 264, which is flattened on its rear side throughout its extension, as will be clearly shown in Figs. 5, 14, and 59. The advantage of this method of securing the 25 member 286 to shaft 264 is that the member 287 coöperates with the flat portion of shaft 264 to hold the member 286 in the upright position, and also by the construction shown in Figs. 8 and 59 it is obvious that by loosening 30 bolt 288 and plate 287 the member 286 can be disengaged entirely from the shaft 264 and removed to any desired position around the intervening members. The upper guide 289 is adapted to coöperate with guide 286 (see

35 Figs. 7, 8, and 59) to control the sheet passing between the two. This upper guide member 289 is adjustably secured to shaft 50 in the following way: Referring to Figs. 8 and 59, the guide member proper, 289, is secured to

40 the yoke 290, which slides over the shaft 50, whereupon the key member 291 is slipped into position, and the bolt 292 passes through the upper arm of the yoke 290 and is threaded into the lower arm, passing freely through 291.

45 The enlarged part of 291 engages in the channel of the shaft 50. Until the bolt 292 is screwed up tight it is obvious that the yoke 290 and the guide 289, supported thereby, may be moved horizontally along the shaft 50 without 50 any rotative movement thereon; but upon the tightening of bolt 292 the same is held in a fixed position on the shaft. By removing the bolt 292 and the keying member 291 it is obvious that guide 289 can be readily removed

55 from the shaft and moved to any desired position around the intervening members. It will be remembered that shaft 50, as described in connection with the drop-roller 49, has a slight rotative movement, and consequently it is ob-

60 vious that guide 289 would have a slight rotative movement with each drop of the roller. It may be explained, however, that this rotative movement of 289 is not sufficient to depress its forward end against the sheet. The 65 guides 286 are especially useful for coöperat-

ing with the front piling and feed-guides when the same are moved backward a considerable distance from the feed-rollers 6 of the receiving device—that is, when the guides 216 are in a position shown in the solid lines in Figs. 13 and 70

14—in which case the guides 286 form a continuation of the horizontal portions 285 of guides 216, as shown in Figs. 8 and 59. These guides 216 and 217 are independently adjustable with respect to each other and are also adjustable with each other independently of the table—that is, the table, as already described, has a vertical adjustment, but also, as will be hereinafter described, has a horizontal adjustment forward and backward and also lateral. 75

With respect to this horizontal adjustment the piling-guides have a forward and backward adjustment, as follows: Referring to Figs. 2 and 7, the guide members 216 are supported by the shafts 218 and 219. The connection with 80 the shaft 218 is by the clamp-boss 220, having set-screw means for securing the lateral adjustment of each member 216 on said shaft 218. The shaft 219 is rotatable in the yoke 221 of said member 216. The shaft 219 is 85 provided at each end with a gear 222. The shaft 218 is provided at each end with a gear 223. Two idlers 224 operate between 222 and 223 to communicate motion from the former to the latter. Horizontal rack-bars 225 and 90 226 are secured to the stationary framework of the machine in duplicate, as shown in Fig. 7, and gears 222 and 223 coöperate with the rack-bars 225 and 226. The shaft 229 is 95 provided with a bevel-gear 227, which coöperates 100 with a bevel-gear 228, which is manipulated by the shaft 229 and hand-wheel 230. It is obvious, therefore, that by the operation of shaft 229 by hand-wheel 230 motion is communicated to the parallel train of gears to 105 cause the same to travel backward or forward, as may be desired, and the consequent backward or forward movement of the front piling and feeding guides 216. The enlarged member 305 (see Fig. 2) limits the forward 110 movement of the gear upon the rack.

Side piling-guide.—The side piling-guide 217 (see Figs. 1, 2, 3, 7, 9, and 57) is mounted on shafts 218 and 219 and has a lateral adjustment on said shaft similar to that shown in 115 connection with the front piling-guides. Piling-guide 217 projects upwardly through the aperture 231 in the table 1.

Feeding-guides.—In order to further control the sheets as they are floated by the air-blast and to keep them straight as they are being combed forwardly, I provide also the feeding-guides, as follows: Guide 232 is adjustably secured upon the opposite side of the table and approximately in an alinement 120 with piling-guide 217. (See Figs. 1, 7, and 59.) This guide 232 is slidably secured in the bracket-sleeve 234. The limit of its downward movement is provided by the pin or projection 293. The bracket-sleeve 234 is slid- 125 130

ably secured to the stationary shaft 233 by the clamp-screw 294 and is adapted to be secured to any desired position upon said shaft. The purpose of supporting the guide 232 so that it will have a free upward movement in sleeve-bracket 234 is to provide for its encountering the table and yielding thereto as the table is raised to deliver the last or bottom sheets of the pile. This feeding-guide 232 extends downwardly a very short distance below the top of the pile of sheets in order to control only the sheets that have been floated by the air-blast. On either side of the rear part of the table are provided two other feeding-guides 214 and 215. (See Figs. 1, 2, 3, 4, 40, and 41.) These guides are adjustably secured to the shafts 179 and 180, respectively, by the clips 235 and 236, which are similar to the one shown more in detail in Fig. 44 and marked 178. As will be observed, these guides 214 and 215 extend only a slight distance below the top of the pile of sheets for the same reason as explained with respect to side guide 217 to control only the sheets which have been floated by the air-blast. These sheets are very sensitive in their movement by cause of being floated by the air-blasts. Especially is this true as to the rear portion of the sheets, the front portion being under the control of the combing-wheels. For this reason these rear side guides 214 and 215 exert an important function in maintaining the sheets perfectly straight and true.

Horizontal adjustment of the table.—The horizontal movement of the table either forward or backward or transversely is accomplished as follows, (see Figs. 2, 3, 49, 50, 51, and 52:) The brackets 95 are carried on the vertical screws 94 on either side of the table. To these brackets 95 are secured the transverse beams 239. Upon the top of one of these beams are seated the rack and guide members 237 and 238. (See Figs. 2, 3, 49, and 50.) These members are provided with flanges projecting downwardly on either side of the beams and are adapted to slide along the top of the beams 239. These members 237 and 238 are also provided with transverse slots 247 and 248, through which ride the angle-irons 240, which rest upon the top of the beams and have a transverse movement on the beams through said slots 247 and 248. Members 237 and 238 are each provided with a rack along its upper surface for the purpose hereinafter described. Member 238 in addition to this is provided with a threaded sleeve 238, (see Fig. 49,) which is adapted to coöperate with the threaded shaft 241, which is supported by the bearing 243, which is secured to one of the beams 239. (See Fig. 52.) This shaft 241 is controlled by the hand-wheel 242. To the angle-irons 240 is secured the platform 1, as best shown in Figs. 2 and 49, and in these angle-irons 240 is rotatably mounted the shaft 244, to which are secured the pinions 245 and 246.

These pinions are adapted to coöperate with the racks in members 237 and 238, respectively. This shaft is squared at one end to receive a hand-lever, such as is shown in Fig. 50^a, for imparting a rotative movement to the same. It is now seen that the platform 1 rests upon and is secured to the angle-irons 240, the lower edges of which rest upon the beams 239 and reside in the slots 247 and 248 of members 237 and 238 and have a sliding movement in the said slots on the top of said beams. By the rotating of the shaft 244 the pinions 245 and 246, which coöperate with the racks in members 237 and 238, cause the forward-and-backward movement of the table. The limit to said forward-and-backward movement of the table is secured by stops 249, Fig. 2, secured to the angle 240 and adapted to encounter either side of beam 239. On the other hand, by turning hand-wheel 242 the threaded shaft 241, which coöperates with the thread in sleeve of member 238, causes the movement of member 238 along the top of beam 239 and because of the engagement of the angle-irons 240 in the slot 248 causes the lateral movement from side to side of the table 1 along the top of the beams.

The purposes of the horizontal adjustments above described are as follows: The forward-and-backward adjustment is for the purpose of securing the desired distance which the sheets must be combed before encountering the valve-trip, this depending upon the quality, weight, or other characteristic of the sheet. The lateral adjustment—that is, from side to side—is for the purpose of bringing the pile in the desired position or in alinement with respect to the receiving mechanism. Of course it is understood that the pile is placed as nearly as possible in the desired position and that this final lateral adjustment is for the perfection of this position.

Lateral adjustment of the combing-wheels.—For the purpose of adjusting the machine for various size sheets it is necessary that the combing-wheels should be capable of lateral adjustment either in the use of two combing-wheels or for the purpose of employing only one combing-wheel, as will be hereinafter described. In the adjustment of the combing-wheel it is also necessary to cause a corresponding lateral adjustment of the drop and feed rollers and the presser-foot. I have found it convenient to connect the operating-head, the drop-roller, and the presser-foot and the intermediate operative mechanism thereof in one common supporting structure, with their coöoperating combing-wheel—that is, the head which operates the combing-wheel and the shaft which operates the presser-foot are supported with their intermediate mechanisms upon the two cross-shafts or rods 184 and 233. The member 80 (see Figs. 5, 10, and 13) is provided with the sleeves 254 and 255, which are slidably mounted on the

rod 233. Extending transversely from the member 80 are the rods 179 and 180, which extend to the rear end of the machine and are provided intermediate the member 80 and its rear end with the bracket 257, which is slidably supported by the cross-rod 184. To the casting 80 is rotatably secured the combing-wheel frame 25. The drop-roller member 3 is also operatively connected therewith through the bracket 198. The valve-trip 8 and the mechanism intermediate the trip and the head are supported by member 80, as are also the rock-shaft 20, the presser-foot, and the intermediate mechanism.

Referring to Fig. 10, it will be noted that rack-serrations are provided in the lower side of rod 233, and a pinion 258 meshing therewith is suitably supported in sleeve 254 and is operated by shaft 259, journaled at its outer end in the bracket 257 and having a squared end 260 (see Figs. 2, 5, and 40) for operating by any suitable means. It will thus be noted that by a rotation of the pinion 259 the casting 80, being integral with the operating-head, the combing-wheel, the drop-roller, and the presser-foot and the operating mechanism are all capable of lateral movement to any desired position and may be locked in said desired position by the clamp-screw 276. (See Fig. 40.) After the proper adjustment of the combing-wheel and its associated mechanism, including the drop-roller, it is necessary to bring the feed-roller into co-operative position therewith.

Supporting mechanism for combing-wheels.—As above stated, the combing-wheels are supported in the combing-wheel frame 25, which frame is journaled in an extension of member 80. The connection between frame 25 and member 80 is shown in Fig. 5 in elevation and in cross-section in Figs. 13 and 24. Referring to Figs. 13 and 24, it will be seen that a sleeve projection 299 of frame 25 is journaled in the member 80 and secured by the nut 297, on the outer end thereof, in such a way that frame 25 has a rotative movement with respect to member 80. As already explained, the combing-wheel 5 is rotatably mounted on the stud 24, which is secured to another part of frame 25. Integral or rigid with this combing-wheel is the gear 79, which meshes with the gear 78, which is rotated by shaft 77. This shaft 77 rotates and is supported in the sleeve 299 of frame 25. The gear 78 is keyed to said shaft 77 and at the same time locked in position with respect to the frame 25 by the key 298, which is provided with two heads, one at either end, one being 300 and the other 301. The said shaft, key, and gear are assembled by first putting the key into position and then slipping the shaft through the gear, it being understood that the keyway of the shaft extends to the end of the shaft and permits the key to slide freely throughout its length.

Valve-trip disengagement.—It should also be noted that before the adjustment of the combing-wheels, and consequently the valve-trip, it is necessary to lift the fingers of the valve-trip out of the extending grooves in the 70 guide member 4 and again in bringing the feed-roller 59, and guide member 4 back to adjustment to co-operate with the valve-trip it is necessary to again reset the valve-trip and return the fingers thereof into the grooves of 75 member 4. For convenience in this operation I have arranged the mechanism as follows: Referring to Figs. 5, 6, and 10, it will be seen that I extend the pivot-pin 9, upon which the valve-trip 8 rotates, outwardly beyond the 80 spring 10. This serves a double purpose. In the first place it prevents the two points of spring connection from passing the dead-center when the spring is on one side of it, and, secondly, when it is desirable to raise the valve-trip and put it out of operation by bringing the spring to the other side of pin 9 the valve-trip is kept raised until the spring is again changed. Thus before the lateral adjustment of the drop-roller and feed-roller it is simply 85 necessary to shift the spring from one side of pin 9, as shown in Fig. 5, to the opposite side of said pin, as shown in Fig. 6, and after the adjustment is made to bring the spring back to its normal position. It might also be added 90 that the lug 261 (see Fig. 13) is so proportioned as to encounter the plate 67 to limit the upward movement of valve-trip 8 when the spring is in the position shown in Fig. 6.

Valve-trip adjustment.—The adjustment 100 and arrangement of the spring 10 and its controlled mechanism is such that the spring acts with the greatest efficiency in the initial position of the valve-trip when said valve-trip is holding the valve-piston in the elevated position. This is because the leverage of the arm of the trip member 8, to which the spring is connected, increases as the trip member is pushed forward and the two points of spring connection approach alignment with the pivot 105 of the valve-trip, the projecting pivot-pin 9 serving, however, normally to prevent the said two points of spring connection passing the dead-center. The tension of spring 10 may be adjusted by moving the member 262, (see Figs. 110 5 and 6,) which is slidably in the bracket 263.

In connection with the lateral adjustment 115 of the combing-wheels to suit the work for which the machine is intended it is also to be noted that as described in connection with the presser-foot said presser-foot has a forward and backward horizontal adjustment, so that the same may also be moved to adapt itself to the requirements of any size sheet.

Construction of combing-wheels.—The specific construction of combing-wheel which I have found convenient in my device may be described as follows: Referring to Figs. 25 and 26, the gear 79, which is integral with the hub member, rotates on stud 24. Secured 120

to this hub member or gear is the rim member 5, which has a double flanged or grooved periphery. In this groove at suitable intervals around the circumference of the wheel 5 are located barrel-shaped rollers 266 axially parallel with the stud 24, the pins 267, upon which the rollers 266 are mounted, being held in position and prevented from turning by the side plate 268, which is secured to the 10 rim member 5 by screws clearly shown in Fig. 26—that is to say, these pins project into holes drilled partly through the walls of rim member 5, the other end of said pin passing entirely through the other flange of said rim 15 member and having a notch cut therein, leaving a shoulder and a flattened surface for engagement against the side plate 268, as shown in Fig. 26, to maintain said pin in position and prevent the turning of the same. An ad- 20 vantage in this construction is to provide for all the wear resulting from the rotation of said rollers to be directly between the roller and the pin and to prevent any wear in the supporting-wheel members, as the pin and roller are the easiest elements to be replaced. 25

Single combing-wheel operation.—Besides the method of using the machine as above described it may be stated that for feeding small or medium size sheets one combing-wheel is sufficient. A single combing-wheel 30 may be used by placing the same so as to operate upon the middle portion of the sheet, using the combing-wheel, however, which is connected with the operating-head mechanism comprising the presser-foot, which controls the height of the pile of sheets hereinabove described. A single combing-wheel may also be used, so as to operate upon the side of the sheet instead of the middle. Such an arrangement 35 is shown in Figs. 20, 21, and 22. This is desirable where there is no blank or unprinted space in the middle of the sheet. In this case the combing-wheel is placed upon the margin of the sheet, as shown in Fig. 20, but there is operated and controlled in connection therewith a pair of drop-rollers 49, which instead of being controlled by two 40 combing-wheels are both controlled solely by one combing-wheel. A further modification 45 in connection with this latter method of operation is the use of the weight 269 and guide-bar 270, which operate on the margin of the paper directly to the rear of the combing-wheel. At the rear of the pile of sheets are 50 the presser-foot and separating-weight 271, which are positioned side by side substantially in alinement with the combing-wheel 5. A special feature of the weight 269 and guide 55 270 is that the guide operating directly against the side edges of the sheets and the weight operating directly on the top margin thereof the weight serves to prevent any tendency in the sheets to curl against the side guide 270, which might be liable due to the

combing power being exerted upon one side 65 of the sheet only. The weight 271 is substantially similar to 186, (shown in Fig. 44,) except that it is supported upon the rod 272, which is a single-armed rod, but is held in substantially the same manner by clamping 70 its horizontal portion with the cross-rod 184 by the clamp 178. By the use of weight 269 the weight 185, as shown in Fig. 44, is dispensed with. In other respects the operation of the device illustrated in Figs. 20, 21, and 75 22 are substantially the same.

What I claim is—

1. In a sheet-feeding machine, the combination of means for combing the sheets, valve-controlled means for disengaging the combing means therefrom and a valve-trip to be encountered by the advancing sheet. 80

2. In a sheet-feeding machine, the combination of means for combing the sheets, pneumatically-operated means for moving the 85 combing means into and out of engagement with the sheets and valve-trip mechanism operated by the advancing sheet for controlling the pneumatically-operated means. 90

3. In a sheet-feeding machine, the combination of pneumatically-operated means for combing sheets, means controlled by the advancing sheet for disengaging the combing means therefrom, a feed-roller and a drop-roller for coöperating therewith and mechanism 95 controlling the operation of the drop-roller whereby the same shall coöperate with the feed-roller only when the combing means is disengaged therefrom. 100

4. In a device for feeding sheets, a plurality 100 of combing-wheels for moving the sheets, the top sheet in advance of the others, pneumatically-controlled means for causing the disengagement of each combing-wheel from the sheets when that part of the sheet controlled 105 by its respective combing-wheel reaches a certain advanced position. 110

5. In a device for feeding sheets, the combination of a plurality of combing-wheels adapted to press upon the pile of sheets as they are rotated, and independently-operative automatic means for controlling each combing-wheel, comprising a valve-trip adapted to be encountered by the advanced edge of the sheet, when the same reaches the required position and pneumatically-controlled mechanism, adapted to be operated upon the actuation of the trip, for causing the disengagement of the combing-wheel from the sheet. 115

6. In a device for feeding sheets, the combination of a combing-wheel adapted to rest against the pile of sheets, as it is being rotated, to comb the sheets forward, the uppermost in advance of the one beneath, pneumatically-controlled means for causing the elevation of the combing-wheel away from contact with the sheets, and a valve-trip adapted 120 to be encountered by the front edge of the 125

sheet when the same reaches the required position to cause the actuation of the same to permit the operation of the elevating means.

7. In a sheet-feeding device, the combination of means for combing the sheets forwardly, the uppermost in advance of those beneath, and a valve-trip having a vertically-depend ing extension to be operated by the advancing sheet when the same reaches the required position and means controlled by said valve-trip and pneumatically controlled to cause disengagement of the combing means from the sheet.

8. In combination with a receiving mechanism, a feeding device for sheets comprising combing means for advancing the sheet toward the receiving mechanism and a valve-trip having a vertically-depend ing extension to be operated by the sheet when combed to the desired position and pneumatically-controlled means controlled by said valve-trip for causing the delivery of the sheet to the receiving mechanism.

9. In a feeding device for sheets, the combination of separable coöperating rollers, means for advancing the sheets between said rollers and automatic pneumatic means controlled by the advanced edge of the sheet to cause the coöperation of said rollers.

10. In a feeding device for sheets, the combination of separable coöperating rollers, means for advancing the sheets between said rollers, automatic pneumatic means controlled by the advanced edge of the sheet to cause the coöperation of said rollers and automatic means for returning the coöperating rollers to normal position.

11. In combination with a receiving device, a feeding device for sheets comprising separable coöperating rollers, means for advancing the sheets between said rollers, automatic pneumatic means controlled by the advanced edge of the sheet to cause the coöperation of said rollers and automatic means for returning the coöperating rollers to the inoperative position.

12. In combination with a receiving device, a feeding device for sheets comprising separable coöperating rollers, means for advancing the sheets between said rollers, automatic pneumatic means controlled by the advanced edge of the sheet to cause the coöperation of said rollers and automatic means acting in unison with the receiving device for returning the coöperating rollers to the inoperative position.

13. In a device for feeding sheets, the combination of coöperating feed-rollers, a plurality of combing-wheels in parallel for moving the sheets toward the feed-rollers, the top sheet in advance of the under ones, and independently-operative automatic pneumatic means for lifting each combing-wheel from engagement with the sheet when that part of the

front edge of the sheet which is in longitudinal alinement with its respective combing-wheel, has reached the required advanced position.

14. In a device for feeding sheets, the combination of coöperating feed-rollers, a plurality of combing-wheels in parallel for moving the sheets toward the feed-rollers, the top sheet in advance of the under ones, independently-operative automatic pneumatic means for lifting each combing-wheel from engagement with the sheet when that part of the front edge of the sheet which is in longitudinal alinement with its respective combing-wheel has reached the required advanced position, and automatic means for causing the coöperation of the feed-rollers when the entire sheet has reached the required position and is perfectly true and has been released by all of the combing-wheels.

15. In a sheet-feeding machine, the combination of means for combing sheets, pneumatically-operated means controlled by the advancing sheet for disengaging the combing means therefrom, a feed-roller and a drop-roller for coöperating therewith and mechanism controlling the operation of the drop-roller so that the same shall coöperate with the feed-roller only during a period of time sufficient to advance the sheet a required distance.

16. In combination with a receiving machine, a machine for feeding sheets thereto, comprising means for combing the sheets, a feed-roller and a drop-roller for coöperating therewith and pneumatically-operated mechanism controlling the operation of the drop-roller whereby the same shall coöperate with the feed-roller to feed the sheet forward when the combing means are disengaged therefrom and further means for controlling the operation of the drop-roller so that it will begin its coöperation with the feed-roller at certain periods only in the operation of the receiving device.

17. In combination with a feeding device for sheets having drop and feed rollers, and a receiving device for the same having drop and feed rollers, means for coupling the action of the drop-rollers of each device so that they shall act relatively and pneumatically-operated means for controlling the said drop-rollers of the feeding device so as to act only when the sheet is in the desired position and further mechanism for permitting said operation only when the receiving device is in that period of its operation adapted to take a sheet.

18. In combination with a receiving mechanism, a device for feeding sheets thereto comprising a pneumatically-operated reciprocating combing-wheel as means for moving the sheets, the topmost in advance of the others, screw means and pawl-and-ratchet means coöperating therewith, for raising the pile of sheets, tripping means for rendering inopera-

tive the pawl-and-ratchet means and pneumatically-operated means controlled by the pile of sheets for controlling the tripping means.

19. In combination with a receiving mechanism, a device for feeding sheets thereto comprising a pneumatically-operated reciprocating combing-wheel as means for moving the sheets, the topmost in advance of the others, means for delivering the top sheet to the receiving device operating relatively therewith, screw means and pawl-and-ratchet means for coöperating therewith, for raising the pile of sheets, tripping means for rendering the pawl-and-ratchet means inoperative and pneumatically-operated means controlled by the pile of sheets for controlling the tripping means.
20. In a device for feeding sheets, the combination of pneumatically-controlled combing means, and means for lubricating or floating said sheets during the combing process, comprising a source of air-supply under pressure and a plurality of air-conducting tubes connected therewith, having nozzles so directed as to deliver currents of air against the edges of the uppermost sheets, said air-currents being controlled by the movement of the sheets.

21. In a device for feeding sheets, the combination of coöperating feed-rollers, means for shifting the sheets to be fed one at a time between said rollers, a valve-trip beyond said rollers adapted to be encountered by the forward edge of the sheet and actuated thereby and pneumatically-operated means controlled by said valve-trip for controlling the coöperation of the feed-rollers.

22. In a device for feeding sheets the combination of means for causing the preliminary forward movement of the sheet, coöperating pairs of feed-rollers normally separated, means for rotating one of each pair of rollers, a valve-trip actuated by the front edge of the sheet near the end of its preliminary movement and pneumatically-operated means controlled by the valve-trip for causing the co-operation of the rollers when the sheet has assumed the desired position between the same.

23. In a device for feeding sheets, a plurality of pairs of coöperating rollers, means for causing the rotation of the same, means for normally holding the coöperating pairs apart, pneumatically-operated means adapted when simultaneously actuated, to move the rollers together, and a plurality of valve-trips operated by the front edge of the sheet when this is perfectly true for actuating the said pneumatically-operated means.

24. In a device for feeding sheets, a plurality of combing-wheels, a plurality of coöperating drop and feed rollers, means for rotating the same, pneumatic means for moving the combing-wheels out of engagement with the sheet and for causing the coöperation of the drop and feed rollers to engage with the sheets and valve-trip means actuated by the

front edge of the advancing sheet for controlling said pneumatic means.

25. In a device for feeding sheets, the combination of combing means for causing the preliminary advance of the sheet, coöperating rollers for continuing the forward movement of the sheet, pneumatically-operated means for controlling the operation of the combing means into and out of engagement with the sheet and also the coöperating movement of the rollers and a valve-trip actuated by the advancing sheet for controlling the pneumatically-operated means.

26. In a device for feeding sheets, the combination of combing means for causing the preliminary forward movement of the sheet, pneumatically-operated means for causing the depression and elevation of the combing means into and out of engagement with the sheet and valve-trip means actuated by the advancing sheet for controlling the pneumatically-operated means.

27. In a device for feeding sheets, the combination of coöperating drop and feed rollers, means for rotating the same, pneumatically-operated means for causing the coöperation of the drop and feed rollers and valve-trip means operated by the advancing sheet for controlling the pneumatically-operated means.

28. In a sheet-feeding device, the combination of coöperating drop and feed rollers, pneumatically-operated means for causing their coöperation, combing means for shifting the sheet to be fed between said rollers, a valve-trip beyond said rollers to be encountered by the forward edge of the sheet to permit the operation of the pneumatically-operated means.

29. In a sheet-feeding device, the combination of means for causing the preliminary forward movement of the sheet, coöperative drop and feed rollers normally separated, means for rotating the rollers, pneumatically-operated means for bringing the coöperating rollers together when the sheet has assumed a certain forward position between the same and a valve-trip adapted to be encountered by the front edge of the sheet for controlling the pneumatically-operated means.

30. In a sheet-feeding device, the combination of coöperating rollers, means for rotating one of said rollers, means for normally holding them apart, pneumatically-operated means when actuated, for moving the rollers together and a valve-trip operated by the front edge of the sheet coming in contact therewith, for permitting the operation of the pneumatically-operated means.

31. In a sheet-feeding device, the combination of coöperating rollers, means for causing the rotation of the same, means for normally holding them apart, pneumatically-operated means for moving the rollers together and tripping means operated by the front edge of the sheet coming in contact therewith, for per-

mitting the operation of the pneumatically-operated means.

32. In combination with a receiving mechanism such as a folding or printing machine, 5 a device for feeding sheets thereto comprising means for combing a pile of sheets, the top-most sheet in advance of the others, pneumatically-operated means, coupled and timed with the receiving mechanism, and controlled 10 by a valve-trip actuated by the advancing edge of the top sheet, for feeding the said sheet forward to the receiving mechanism.

33. In combination with a receiving mechanism such as a folding or printing machine, 15 15 a device for feeding sheets thereto comprising means for combing the pile of sheets, the top-most sheet in advance of the others, pneumatically-operated means for causing the feeding of the top sheet to the receiving mechanism, 20 and valve-trip control for said pneumatic means operated by the advancing edge of the top sheet while being combed.

34. In combination with a receiving mechanism, such as a folding or printing machine, 25 25 a device for feeding sheets thereto comprising means for combing the pile of sheets, the top-most sheet in advance of the others, pneumatically-controlled mechanism for feeding the top sheet to the receiving mechanism, a valve-trip 30 for said pneumatic control operated by the advancing edge of the top sheet while being combed, and mechanical means for coupling the operation of the feeding means to act in unison with the operation of the receiving 35 mechanism.

35. In combination with a receiving mechanism such as a folding or printing machine, a device for feeding sheets thereto, comprising means for combing the sheets forward, the top 40 sheet in advance of the under ones, means for engaging with the top sheet to feed it to the receiving mechanism, pneumatically-operated means for controlling the operation of the feeding means, a valve-trip actuated by the 45 front edge of the top sheet, as it is being combed forward, for controlling the operation of the pneumatic means.

36. In combination with a receiving mechanism, such as a folding or printing machine, 50 50 a device for feeding sheets thereto comprising means for combing the sheets forward, the top sheet in advance of the others, means for engaging with the top sheet to feed it to the receiving mechanism, pneumatically-operated 55 means for controlling the operation of the feeding means, a valve-trip actuated by the front edge of the top sheet as it is being combed forward for controlling the operation of the pneumatically-operated means and mechanical 60 means for coupling the operation of the feeding means to act in unison with the operation of the receiving means.

37. In combination with a receiving mechanism, such as a folding or printing machine, 65 a device for feeding sheets thereto comprising

means for combing the sheets forward, the top sheet in advance of the others, means for engaging with the top sheet to feed it to the receiving mechanism, pneumatically-operated means for controlling the operation of the feeding means, a valve-trip actuated by the front edge of the top sheet as it is being combed forward, for controlling the operation of the pneumatically-operated means and means controlled by the pile of sheets in coöperation 70 with the pneumatically-operated means for maintaining the pile of sheets at an approximately constant height.

38. In combination with a receiving mechanism, such as a folding or printing machine, 80 a device for feeding sheets thereto comprising means for combing the sheets forward, the top sheet in advance of the others, means for engaging with the top sheet to feed it to the receiving mechanism, pneumatically-operated 85 means for controlling the operation of the feeding means, a valve-trip actuated by the front edge of the top sheet as it is being combed forward, for controlling the operation of the pneumatic means, and pneumatically-operated 90 means controlled by the pile of sheets for maintaining said pile at an approximately constant height.

39. In combination with a receiving mechanism, such as a folding or printing machine, 95 95 a device for feeding sheets thereto comprising means for combing the sheets forward, the top sheet in advance of the others, means for engaging with the top sheet to feed it to the receiving mechanism, pneumatically-operated 100 means for controlling the operation of the feeding means, a valve-trip actuated by the front edge of the top sheet as it is being combed forward for controlling the operation of the pneumatically-operated means, and 105 means for injecting a current of air between the edges of the sheets to assist in their separation.

40. In combination with a receiving mechanism, such as a folding or printing machine, 110 110 a device for feeding sheets thereto comprising means for combing the sheets forward, the top sheet in advance of the others, means for engaging with the top sheet to feed it to the receiving mechanism, pneumatically-operated 115 means for controlling the operation of the feeding means, a valve-trip actuated by the front edge of the top sheet as it is being combed forward, for controlling the operation of the pneumatic means and means for injecting 120 currents of air in opposite directions between the edges of the sheets to assist in their separation.

41. In a sheet-feeding device, the combination of a combing-wheel, a presser-foot at the 125 rear thereof, pneumatically-operated means for raising and lowering the combing-wheel and spring means connected between the pneumatically-operated means and the presser-foot. 130

42. In a sheet-feeding machine, the combination of means for combing the sheets, a presser-foot for engaging the sheets at the rear of the combing means, pneumatically-operated means for raising and lowering the combing means and spring-controlled mechanism operating between the pneumatically-operated means and the presser-foot.
43. In a sheet-feeding machine, the combination of a combing-wheel, a rock-shaft for raising and lowering the same, a presser-foot and a rock-lever support therefor, spring-controlled mechanism operating between the rock-shaft and the rock-lever support and double pivoted connecting means between the presser-foot and the rock-lever support.
44. In a sheet-feeding machine, the combination of a combing-wheel and automatic means for raising and lowering the same out of and into engagement with the sheets and a manually-operative cam acting upon said lifting mechanism as means for arbitrarily raising and lowering said combing-wheel.
45. In a sheet-feeding machine, the combination of combing means for moving the sheets one in advance of the other, means for blowing air between the edges of the sheets to assist in their separation and manually-operative means for arbitrarily disengaging the combing means from the sheets and at the same time shutting off the air-blast.
46. In a machine for feeding sheets, the combination of a rotating combing-wheel, pneumatically-operative means for raising and lowering the same, means for blowing air between the sheets to assist in their separation automatic means operated by the advancing sheets for controlling the operation of the pneumatic means and manually-operative means for arbitrarily raising the combing-wheels at the same time shutting off the air-supply.
47. In a machine for feeding sheets, the combination of combing means, a presser-foot located at the rear thereof and a fixed rod, adjustably secured to the framework of the machine, having a vertical extension and provided with a presser-weight, slideable thereon, for coöperating with the presser-foot.
48. In a machine for feeding sheets, the combination of means for combing the sheets, a member adjustably secured to the machine provided with a vertically-movable presser-weight resting upon the sheets to the rear of the combing means for controlling the rate of combing.
49. In a machine for feeding sheets, the combination of means for combing the sheets, an adjustable member provided with a vertically-movable presser-weight resting upon the sheets to the rear of the combing means for controlling the distance which one sheet is moved in advance of the other.
50. In a machine for feeding sheets, the combination of means for combing the sheets, an adjustable member provided with a vertically-movable presser-weight resting upon the sheets to the rear of the combing means for controlling the rate of combing and for controlling the distance which one sheet is moved in advance of the other.
51. In a machine for feeding sheets, the combination of means for combing the sheets, and, at the rear thereof, a plurality of presser-weights resting upon the sheets one to the rear of the other.
52. In a machine for feeding sheets, the combination of means for combing the sheets, and a plurality of presser-weights resting upon the sheets to the rear of the combing means so disposed that one shall contribute in steadyng the pile of sheets, and another so disposed as to control the distance which one sheet is moved in advance of the other.
53. In a machine for feeding sheets, the combination of means for combing the sheets, and a plurality of presser-weights resting upon the sheets to the rear of the combing means, one so disposed as to contribute in steadyng the sheets and controlling the rate of combing, another so disposed as to control the distance which one sheet is moved in advance of the other.
54. In a machine for feeding sheets, the combination of means for combing the sheets, a plurality of presser-weights resting upon the sheets to the rear of the combing-wheel, said weights disposed in approximate alinement in the direction of the movement of the sheets, one resting upon the entire pile while the other rests upon the pile to the rear of the first few sheets.
55. In a machine for feeding sheets, the combination of means for combing the sheets, a member adjustably secured behind the combing means provided with a vertically-movable presser-weight resting upon the sheets for controlling the rate of combing and means for varying the pressure of said weight.
56. In a machine for feeding sheets, the combination of means for combing the sheets, a member adjustably secured behind the combing means provided with a vertically-movable presser-weight resting upon the sheets for controlling the distance which one sheet is moved in advance of the other and means for varying the pressure of said weight.
57. In a machine for feeding sheets, the combination of means for combing the sheets, a member adjustably secured behind the combing means provided with a vertically-movable presser-weight resting upon the sheets for controlling the rate of combing and for controlling the distance which one sheet is moved in advance of the other and means for varying the pressure of said weight.
58. In a machine for feeding sheets, the combination of means for combing the sheets, a plurality of presser-weights located behind said combing means and resting upon the

sheets one to the rear of the other, and means for varying the pressure of one or more of said weights.

59. In a machine for feeding sheets, the combination of means for combing the sheets, a plurality of presser-weights resting upon the sheets to the rear of the combing means so disposed that one shall contribute in steadyng the pile of sheets, another so disposed as to control the distance which one sheet is moved in advance of the other, and means for varying the pressure of one or more of said weights.

60. In a machine for feeding sheets, the combination of means for combing the sheets, a plurality of presser-weights resting upon the sheets to the rear of the combing means, one so disposed as to contribute in steadyng the sheets and controlling the rate of combing, another so disposed as to control the distance which one sheet is moved in advance of the other, and means for varying the pressure of one or more of said weights.

61. In a machine for feeding sheets, the combination of means for combing the sheets, a plurality of presser-weights resting upon the sheets to the rear of the combing-wheel, said weights disposed in approximate alinement in the direction of the movement of the sheets, one resting upon the entire pile while the other rests upon the pile to the rear of the first few sheets, and means for varying the pressure of one or more of said weights.

62. In a machine for feeding sheets, the combination of combing means, means for blowing air between the sheets to assist in their separation, a presser-foot located at the rear thereof and a presser-weight coöperating therewith to steady the sheets.

63. In a machine for feeding sheets, the combination of combing means, means for blowing air between the sheets to assist in their separation, a presser-foot located at the rear thereof, a presser-weight coöperating therewith to steady the sheets and adjustable guides for engaging with the sides of the sheets to coöperate in maintaining their position.

64. In a sheet-feeding machine, the combination of a combing-wheel, pneumatically-operated means for raising and lowering the same, valve-trip mechanism operated by the advancing sheet for controlling the operation of the pneumatic means, a feed-roller and a coöperating drop-roller for feeding the sheet after it has been advanced a sufficient distance by the combing-wheel, a presser-foot for steadyng the sheet, a fixed support for the above-recited mechanisms and means for so connecting said mechanisms as to permit of their simultaneous lateral adjustment upon said fixed support.

65. In a sheet-feeding machine, the combination of a combing-wheel, a presser-weight, a presser-foot and means for raising the presser-foot when the combing-wheel is lowered and

lowering the presser-foot when the combing-wheel is raised.

66. In a sheet-feeding machine, the combination of a table for holding the pile of sheets, a combing-wheel, a presser-foot, pneumatically-operated means for causing the reciprocative movement of the combing-wheel and the presser-foot, pawl-and-ratchet-operated means for raising the table, tripping means for rendering inoperative the pawl-and-ratchet means and means operated by the presser-foot controlled by the pile of sheets for controlling the tripping means.

67. In a sheet-feeding machine, the combination of means for combing the sheets, pneumatically-operative means for moving the combing means into and out of engagement with the pile of sheets, valve-trip mechanism operated by the advancing sheet for controlling the pneumatically-operative means, automatic means for regulating the air-pressure operating the pneumatic means.

68. In a sheet-feeding machine, the combination of means for combing the sheets, pneumatically-operative means for moving the combing means into and out of engagement with the sheets, valve-trip mechanism operated by the advancing sheet for controlling the pneumatically-operative means, adjustable means for automatically regulating the air-pressure operating the pneumatic means.

69. In a sheet-feeding machine, the combination of means for combing the sheets, pneumatically-operative means for moving the combing means into and out of engagement with the sheets, valve-trip mechanism operated by the advancing sheet for controlling the pneumatically-operative means, and a pressure-regulating reservoir and air-cushion connected with the pneumatically-operative means.

70. In a sheet-feeding machine, the combination of means for combing the sheets, pneumatically-operative means for moving the combing means into and out of engagement with the sheets, valve-trip mechanism operated by the advancing sheet for controlling the pneumatically-operative means, valve-controlled means for blowing air between the edges of the sheets, and automatic means for regulating the air-pressure operating the pneumatic means.

71. In a sheet-feeding machine, the combination of means for combing the sheets, pneumatically-operative means for moving the combing means into and out of engagement with the sheets, valve-trip mechanism operated by the advancing sheet for controlling the pneumatically-operative means, valve-controlled means for blowing air between the edges of the sheets, and automatic means for regulating the air-pressure operating the pneumatic means.

72. In a sheet-feeding machine, the combi-

nation of means for combing the sheets, pneumatically-operative means for moving the combing means into and out of engagement with the sheets, valve-trip mechanism, operated by the advancing sheet, for controlling the pneumatically-operative means, valve-controlled means for blowing air between the edges of the sheets, and a pressure-regulating reservoir and air-cushion connected with the 10 pneumatically-operative means.

73. In combination with a sheet-feeding machine a drop-roller and a feed-roller, a rotating shaft for the feed-roller, the feed-roller comprising two members, the inner member 15 keyed to the rotating shaft and provided with two peripheral grooves and a series of cam-pockets peripherally arranged between said grooves, the outer member surrounding said inner member and forming the outer contacting 20 rim of the roller, antifriction-balls seated in the grooves and engaging the inner surface of the outer member, antifriction-balls also seated in the cam-pockets adapted to permit of movement of the outer member independently of the inner member in one direction but to lock the outer member with the inner member to prevent independent movement in the other direction.

74. In combination with a sheet-feeding machine means for combing the sheets, an adjustable guide engaging the side edges of the sheets to the rear of the combing-wheel and a presser-weight slidably mounted on said guide for pressing upon the top of the pile of 35 sheets.

75. In a sheet-feeding machine, the combination of means for combing the sheets, a member secured to said machine to the rear of the combing means, having lateral and longitudinal adjustment with respect thereto, provided with a plurality of vertically-depend- 40 ing extensions, each extension provided with a presser-weight slidable thereon.

76. In a combing-wheel for sheet-feeding machines, the combination of a member provided with a double flange forming a peripheral channel, a plurality of axially-parallel rollers located in said peripheral channel, and supporting-pins for said rollers fixed with respect to the sides of the peripheral channel.

77. In a combing-wheel for sheet-feeding machines, the combination of a member provided with a double flange forming a peripheral channel, a plurality of axially-parallel 55 rollers located in said peripheral channel, supporting-pins for said rollers fixed with respect to the sides of the peripheral channel, and pins for securing said rollers in said peripheral groove so secured that all friction shall be 60 between the rollers and their supporting-pins.

78. In a combing-wheel, the combination of a hub member and a rim member, the hub member provided with gear-teeth, the rim member provided with a peripheral channel 65 having rollers seated therein and bearing-pins

for said rollers provided with shoulders and a plate member for coöperating therewith to prevent end movement of the pins.

79. A combing-wheel provided with a peripheral channel, rollers seated in said channel, bearing-pins for said rollers provided with recessed ends and a plate member secured to the rim member in such a way as to engage the recessed end of each bearing-pin to prevent the turning of the same. 75

80. In a combing-wheel, the combination of a hub member, and a rim member supported thereon, the hub member provided with a pinion, the rim member provided with a peripheral channel, a plurality of rollers seated in 80 said channel, bearing-pins for said rollers and means for preventing the turning of the bearing-pins.

81. A combing-wheel comprising a hub member provided with gear-teeth upon its 85 outer periphery and a circular flange on its web intermediate its axis and periphery, and a rim member detachably secured to said web and flange, provided with a peripheral channel having rollers seated therein. 90

82. A combing-wheel comprising a hub member, and a rim member detachably secured thereto, provided with a peripheral channel having rollers seated therein, bearing-pins for said rollers and means for preventing 95 the turning of said pins.

83. A combing-wheel comprising a hub member provided with peripheral gear-teeth, and a circular flange intermediate its axis and periphery, and a rim member detachably secured thereto against said flange provided with a peripheral channel having rollers seated 100 therein.

84. A combing-wheel comprising a hub member provided with a pinion, and a rim member detachably secured thereto provided with a peripheral channel having rollers seated therein, bearing-pins for said rollers and means for preventing the turning of said pins. 105

85. A combing-wheel comprising a hub member, and a rim member detachably secured thereto provided with a peripheral channel having rollers seated therein, bearing-pins for said rollers having one end recessed, and a circular plate secured to the side of the 115 rim member so as to engage in the recesses of each pin to prevent the turning of the same.

86. A combing-wheel comprising a hub member, and a rim member detachably secured thereto provided with a peripheral channel having rollers seated therein, bearing-pins for said rollers having one end recessed and a circular plate detachably secured to the side of the rim member so as to engage in the recesses of each pin to prevent the turning 125 of the same.

87. A combing-wheel comprising a hub member provided with a pinion, a rim member, detachably secured thereto provided with a peripheral channel having rollers seated 130

therein, bearing-pins for said rollers having one end recessed or flattened and a circular plate secured to the side of the rim member so as to engage in the recesses of each pin to prevent the turning of the same.

88. A combing-wheel comprising a hub member provided with a pinion, a rim member, detachably secured thereto provided with a peripheral channel having rollers seated therein, bearing-pins for said rollers having one end provided with a flattened surface and a circular plate detachably secured to the side of the rim member so as to engage in the recesses of each pin to prevent the turning of the same.

89. A combing-wheel a hub member provided with a circular shoulder or projection, and a rim member detachably secured to the hub member, surrounding and fitting over the circular shoulder, and provided with a circumferential channel having a plurality of rollers seated therein.

90. In a sheet-feeding device, the combination of reciprocative combing mechanism, pneumatically-operated means for controlling the reciprocative movement of said mechanism, a valve for controlling the pneumatically-operated means and means whereby the advancing sheet controls the valve.

91. In a sheet-feeding device, the combination of reciprocative combing and presser-foot mechanism, pneumatically-operated means for controlling the reciprocative movement of said mechanism, a valve for controlling the pneumatically-operated means and means whereby the advancing sheet controls said valve.

92. A sheet-feeding device comprising pneumatically-controlled mechanism, a valve for controlling said mechanism, and a tripping member operating between the advancing sheet and the valve as means whereby the advancing sheet controls said valve.

93. A sheet-feeding device comprising pneumatically-controlled mechanism, a valve for controlling said mechanism, and a spring-controlled tripping member operating between the advancing sheet and the valve as means whereby the advancing sheet controls said valve.

94. A sheet-feeding device comprising pneumatically-controlled mechanism, a valve for controlling said mechanism, and an adjustable spring-controlled tripping member operating between the advancing sheet and the valve as means whereby the advancing sheet controls said valve.

95. A sheet-feeding device comprising pneumatically-controlled mechanism, a valve for controlling said mechanism, and a spring-balanced tripping member operating between the advancing sheet and the valve as means whereby the advancing sheet controls said valve.

96. A sheet-feeding device comprising

pneumatically-controlled mechanism, a valve for controlling said mechanism, and an adjustable spring-balanced tripping member operating between the advancing sheet and the valve as means whereby the advancing sheet controls said valve.

97. A sheet-feeding device comprising pneumatically-controlled mechanism, a valve for controlling said mechanism, and a swinging member provided with a plurality of projections adapted to be encountered by the advancing sheet as means whereby the advancing sheet controls said valve.

98. A sheet-feeding device comprising pneumatically-controlled mechanism, a valve for controlling said mechanism, and a swinging member provided with a plurality of projections operating in a recessed surface and adapted to be encountered by the advancing sheet as means whereby the advancing sheet controls said valve.

99. A sheet-feeding device comprising pneumatically-controlled mechanism, a valve for controlling said mechanism, and a spring-balanced swinging member provided with a plurality of projections adapted to be encountered by the advancing sheet as means whereby the advancing sheet controls said valve.

100. A sheet-feeding device comprising pneumatically-controlled mechanism, a valve for controlling said mechanism, and a spring-balanced swinging member provided with a plurality of projections adapted to be encountered by the advancing sheet as means whereby the advancing sheet controls said valve.

101. A sheet-feeding device comprising pneumatically-controlled drop and feed roller mechanism, a valve for controlling said mechanism, and means whereby the advancing sheet controls said valve.

102. In a sheet-feeding device the combination of drop and feed roller mechanism and means for operating the same, pneumatically-actuated means for controlling said operation, a valve for controlling the pneumatic means, and means controlled by the advancing sheet for actuating said valve.

103. A sheet-feeding device comprising pneumatically-controlled drop and feed roller mechanism, a valve for controlling said mechanism, and a tripping member operating between the advancing sheet and the valve as means whereby the advancing sheet controls said valve.

104. A sheet-feeding device comprising pneumatically-controlled drop and feed roller mechanism, a valve for controlling said mechanism, and a spring-controlled tripping member operating between the advancing sheet and the valve as means whereby the advancing sheet controls said valve.

105. A sheet-feeding device comprising pneumatically-controlled drop and feed roller mechanism, a valve for controlling said mechanism, and an adjustable spring controlled

tripping member operating between the advancing sheet and the valve as means whereby the advancing sheet controls said valve.

106. In a sheet-feeding device the combination of drop and feed roller mechanism, and means for operating the same, pneumatically-actuated means for controlling said operation, a valve for controlling said pneumatic means, and a spring-balanced tripping member operating between the advancing sheet and the valve as means whereby the advancing sheet controls said valve.

107. In a sheet-feeding device the combination of drop and feed roller mechanism, and means for operating the same, pneumatically-actuated means for controlling said operation, a valve for controlling said pneumatic means, and an adjustable spring-balanced tripping member operating between the advancing sheet and the valve as means whereby the advancing sheet controls said valve.

108. A sheet-feeding device comprising pneumatically-controlled drop and feed roller mechanism, a valve for controlling said mechanism, and a swinging member provided with a plurality of projections adapted to be encountered by the advancing sheet as means whereby the advancing sheet controls said valve.

109. A sheet-feeding device comprising pneumatically-controlled drop and feed roller mechanism, a valve for controlling said mechanism, and a swinging member provided with a plurality of projections operating in a recessed surface and adapted to be encountered by the advancing sheet as means whereby the advancing sheet controls said valve.

110. A sheet-feeding device comprising pneumatically-controlled drop and feed roller mechanism, a valve for controlling said mechanism, and a spring-balanced swinging member provided with a plurality of projections adapted to be encountered by the advancing sheet as means whereby the advancing sheet controls said valve.

111. In a sheet-feeding device the combination of drop and feed roller mechanism, and means for operating the same, pneumatically-actuated means controlling said operation, a valve for controlling said pneumatic means, and a spring-balanced swinging member provided with a plurality of projections adapted to be encountered by the advancing sheet as means whereby the advancing sheet controls said valve.

112. A sheet-feeding device comprising pneumatically-controlled combing mechanism, a valve for controlling said mechanism, and means whereby the advancing sheet controls said valve.

113. A sheet-feeding device comprising pneumatically-operated combing mechanism, a valve for controlling said mechanism, and means whereby the advancing sheet actuates said valve.

114. A sheet-feeding device comprising pneumatically-controlled combing mechanism, a valve for controlling said mechanism, and a tripping member operating between the advancing sheet and the valve as means whereby the advancing sheet controls said valve. 70

115. A sheet-feeding device comprising pneumatically-controlled combing mechanism, a valve for controlling said mechanism, and a spring-controlled tripping member operating between the advancing sheet and the valve as means whereby the advancing sheet controls said valve. 75

116. A sheet-feeding device comprising pneumatically-controlled combing mechanism, a valve for controlling said mechanism, and an adjustable spring-controlled tripping member operating between the advancing sheet and the valve as means whereby the advancing sheet controls said valve. 80

117. In a sheet-feeding device the combination of reciprocative combing mechanism pneumatically-actuated means for controlling said reciprocation, a valve for controlling said pneumatic means, and a spring-balanced tripping member operating between the advancing sheet and the valve as means whereby the advancing sheet controls said valve. 90

118. A sheet-feeding device comprising pneumatically-controlled combing mechanism, a valve for controlling said mechanism, and an adjustable spring-balanced tripping member operating between the advancing sheet and the valve as means whereby the advancing sheet controls said valve. 95

119. A sheet-feeding device comprising pneumatically-controlled combing mechanism, a valve for controlling said mechanism, and a swinging member provided with a plurality of projections adapted to be encountered by the advancing sheet as means whereby the advancing sheet controls said valve. 100

120. A sheet-feeding device comprising pneumatically-controlled combing mechanism, a valve for controlling said mechanism, and a swinging member provided with a plurality of projections operating in a recessed surface and adapted to be encountered by the advancing sheet as means whereby the advancing sheet controls said valve. 110

121. A sheet-feeding device comprising pneumatically-controlled combing mechanism, a valve for controlling said mechanism, and a spring-balanced swinging member provided with a plurality of projections adapted to be encountered by the advancing sheet as means whereby the advancing sheet controls said valve. 115

122. In a sheet-feeding device the combination of reciprocative combing mechanism pneumatically-actuated means for controlling said reciprocation, a valve for controlling said pneumatic means, and a spring-balanced swinging member provided with a plurality of projections adapted to be encountered by the advancing sheet as means whereby the advancing sheet controls said valve. 125

130

- the advancing sheet as means whereby the advancing sheet controls said valve.
123. In a sheet-feeding device the combination of drop and feed roller and reciprocative 5 combing mechanism, pneumatic means for controlling the operation of said mechanism, a valve for controlling the pneumatic means, and means whereby the advancing sheet controls said valve.
124. A sheet-feeding device comprising pneumatically-operated drop and feed roller and combing mechanism, a valve in the pneumatic controlling means, and means whereby the advancing sheet actuates said valve.
125. A sheet-feeding device comprising pneumatically-controlled drop and feed roller and combing mechanism, a valve for controlling said mechanism, and a tripping member operating between the advancing sheet and the valve as means whereby the advancing sheet controls said valve.
126. A sheet-feeding device comprising pneumatically-controlled drop and feed roller and combing mechanism, a valve for controlling said mechanism, and a spring-controlled tripping member operating between the advancing sheet and the valve as means whereby the advancing sheet controls said valve.
127. A sheet-feeding device comprising pneumatically-controlled drop and feed roller and combing mechanism, a valve for controlling said mechanism, and an adjustable spring-controlled tripping member operating between the advancing sheet and the valve as means whereby the advancing sheet controls said valve.
128. A sheet-feeding device comprising pneumatically-controlled drop and feed roller and combing mechanism, a valve in the pneumatic controlling means, and a spring-balanced tripping member operating between the advancing sheet and the valve as means whereby the advancing sheet controls said valve.
129. A sheet-feeding device comprising pneumatically-controlled drop and feed roller and combing mechanism, a valve for controlling said mechanism, and an adjustable spring-balanced tripping member operating between the advancing sheet and the valve as means whereby the advancing sheet controls said valve.
130. A sheet-feeding device comprising pneumatically-controlled drop and feed roller and combing mechanism, a valve for controlling said mechanism, and a swinging member provided with a plurality of projections adapted to be encountered by the advancing sheet as means whereby the advancing sheet controls said valve.
131. A sheet-feeding device comprising pneumatically-controlled drop and feed roller and combing mechanism, a valve for controlling said mechanism, and a swinging member provided with a plurality of projections operating in a recessed surface and adapted to be encountered by the advancing sheet as means whereby the advancing sheet controls said valve.
132. A sheet-feeding device comprising pneumatically-controlled drop and feed roller 70 and combing mechanism, a valve for controlling said mechanism, and a spring-balanced swinging member provided with a plurality of projections adapted to be encountered by the advancing sheet as means whereby the 75 advancing sheet controls said valve.
133. A sheet-feeding device comprising pneumatically-controlled drop and feed roller and combing mechanism, a valve in said pneumatic controlling means, and a spring-balanced swinging member provided with a plurality of projections adapted to be encountered by the advancing sheet to cause the actuation of said valve.
134. A sheet-feeding device comprising 85 pneumatically-controlled drop and feed roller and combing mechanism, a valve in said pneumatic controlling means, and a spring-balanced swinging member provided with a plurality of projections operating in a recessed 90 surface and adapted to be encountered by the advancing sheet to permit the actuation of said valve.
135. A sheet-feeding device comprising pneumatically-controlled drop and feed roller 95 and combing mechanism, a valve for controlling said mechanism, and a spring-balanced swinging member provided with a plurality of projections operating in a recessed surface and adapted to be encountered by the advancing sheet as means whereby the advancing 100 sheet controls said valve.
136. In combination with means for combing sheets, pneumatic means for raising the combing means from the sheets, comprising 105 an air-chamber provided with a movable diaphragm and a piston actuated thereby, and means controlled by the advancing sheet for admitting compressed air to the air-chamber.
137. In combination with means for combing sheets, pneumatic means for raising the combing means from the sheets comprising a compressed-air supply, an air-chamber connected therewith provided with a movable diaphragm and a piston actuated thereby, a 115 valve for controlling the admission of air to the chamber and a valve-trip thereto controlled by the advancing sheet.
138. In combination with means for combing sheets, pneumatic means for raising the 120 combing means from the sheets, comprising an air-chamber provided with a movable diaphragm and a piston actuated thereby, means for communicating movement from the diaphragm-piston to the combing means, and 125 means controlled by the advancing sheet for admitting compressed air to the air-chamber.
139. In combination with means for combing sheets, pneumatic means for raising the combing means from the sheets, comprising 130

an air-chamber provided with a movable diaphragm and a piston actuated thereby, and means controlled by the advancing sheet for admitting and discharging air-pressure to and from the air-chamber.

140. In combination with means for combing sheets, pneumatic means for moving the combing means into and out of engagement with the sheets, comprising an air-chamber 10 provided with a movable diaphragm, means for admitting and discharging compressed air to and from said chamber to cause the movement of the diaphragm, and means for communicating the movement of the diaphragm 15 to the combing means.

141. In combination with means for combing sheets, pneumatic means for moving the combing means into and out of engagement with the sheets, comprising an air-chamber 20 provided with a movable diaphragm, valve-controlled means for admitting and discharging compressed air to and from said chamber to cause the movement of the diaphragm, and means for communicating the movement of 25 the diaphragm to the combing means.

142. In combination with means for combing sheets, means for moving the combing means into and out of engagement with the sheets, comprising an air-chamber provided 30 with a movable diaphragm, a source of air-pressure, a valve for controlling the admission of said air-pressure to said chamber, and a tripping member actuated by the advancing sheet for operating said valve.

143. In combination with means for combing sheets, means for moving the combing means into and out of engagement with the sheets, comprising an air-chamber provided 35 with a movable diaphragm, a source of air-pressure, a valve for controlling the admission and discharge of said air-pressure to and from said chamber, and a tripping member actuated by the advancing sheet for operating said valve.

144. In combination with means for combing sheets, means for moving the combing means into and out of engagement with the sheets, comprising an air-chamber provided 40 with a movable diaphragm and means for communicating movement therefrom to the combing means, a source of air-pressure, a valve for controlling the admission of said air-pressure to said chamber, and a tripping member actuated by the advancing sheet for operating said 45 valve.

145. In combination with means for combing sheets, means for moving the combing means into and out of engagement with the sheets, comprising an air-chamber provided 50 with a movable diaphragm and means for communicating movement therefrom to the combing means, a source of air-pressure, a valve for controlling the admission and discharge of said air-pressure to and from said chamber,

and a tripping member actuated by the advancing sheet for operating said valve. 65

146. In combination with means for combing sheets, pneumatic means for moving the combing means into and out of engagement with the sheets, means for controlling the pneumatic means, comprising a valve-piston and means for operating the same controlled by the advancing sheet, for opening and closing communication between the source of air-pressure and the pneumatically-operated 70 means. 75

147. In combination with means for combing sheets, pneumatic means for moving the combing means into and out of engagement with the sheets, means for controlling the pneumatic means, comprising a valve-piston and means for operating the same controlled by the advancing sheet, for opening and closing communication between the pneumatically-operated means and the source of air-pressure 80 and the outside atmosphere respectively. 85

148. In combination with means for combing sheets, pneumatic means for moving the combing means into and out of engagement with the sheets, means for controlling the pneumatic means, comprising a vertically-movable valve-piston and means for operating the same controlled by the advancing sheet, for opening and closing communication between the source of air-pressure and the pneumatically-operated 90 means. 95

149. In combination with means for combing sheets, pneumatic means for moving the combing means into and out of engagement with the sheets, means for controlling the pneumatic means, comprising a valve-piston and tripping means for operating the same controlled by the advancing sheet, for opening and closing communication between the source of air-pressure and the pneumatically-operated 100 means. 105

150. In combination with means for combing sheets, pneumatic means for moving the combing means into and out of engagement with the sheets, means for controlling the pneumatic means, comprising a valve-piston and tripping means for operating the same controlled by the advancing sheet, for opening and closing communication between the pneumatically-operated means and the source of air-pressure 110 and the outside atmosphere respectively. 115

151. In combination with means for combing sheets, pneumatic means for moving the combing means into and out of engagement with the sheets, means for controlling the pneumatic means, comprising a vertically-movable valve-piston and tripping means for operating the same controlled by the advancing sheet, for opening and closing communication between the source of air-pressure and the pneumatically-operated 120 means. 125

152. In combination with means for comb-

- ing sheets, pneumatic means for moving the combing means into and out of engagement with the sheets, means for controlling the pneumatic means, comprising a valve-piston and a 5 pivoted spring-controlled lever for operating the same controlled by the advancing sheet, for opening and closing communication between the source of air-pressure and the pneumatically-operated means.
- 10 153. In combination with means for combing sheets, pneumatic means for moving the combing means into and out of engagement with the sheets, means for controlling the pneumatic means, comprising a valve-piston and a 15 pivoted spring-controlled lever for operating the same controlled by the advancing sheet, for opening and closing communication between the pneumatically-operated means and the source of air-pressure and the outside 20 atmosphere respectively.
154. In combination with means for combing sheets, pneumatic means for moving the combing means into and out of engagement with the sheets, means for controlling the pneumatic means, comprising a vertically-movable 25 valve-piston and a pivoted spring-controlled lever for operating the same controlled by the advancing sheet, for opening and closing communication between the source of air-pressure 30 and the pneumatically-operated means.
155. In combination with means for combing sheets, pneumatic means for moving the combing means into and out of engagement with the sheets, means for controlling the pneumatic means comprising a valve-piston and a 35 pivoted spring-controlled lever for operating the same controlled by the advancing sheet.
156. In combination with means for combing sheets, pneumatic means for moving the 40 combing means into and out of engagement with the sheets, means for controlling the pneumatic means, comprising a vertically-movable valve-piston and a pivoted spring-controlled lever as tripping means for operating the same 45 controlled by the advancing sheet.
157. In combination with means for combing sheets, pneumatic means for moving the combing means into and out of engagement with the sheets, means for controlling the pneumatic means, comprising a valve-piston and a 50 pivoted trip operated by the advancing sheet for actuating the piston.
158. In combination with a receiving device, a sheet-feeding device comprising pneumatic- 55 ally-controlled drop and feed roller mechanism controlled by the advancing sheet, and further controlled by mechanism operated by the receiving device.
159. In combination with a receiving device, 60 a sheet-feeding device comprising pneumatically-controlled drop and feed roller mechanism controlled by the advancing sheet, and further controlled by mechanism acting in unison with the receiving device.
160. In combination with a receiving device-65 a sheet-feeding device comprising pneumatically-controlled drop and feed roller mechanism controlled by the advancing sheet, and means for preventing the operation of the same except when the receiving device is in 70 the required position.
161. In combination with a receiving device, a sheet-feeding device comprising pneumatically-controlled drop and feed roller mechanism controlled by the advancing sheet, and 75 further controlling means for said drop and feed roller to permit the coöperation of the same only at the required moment in the cycle of operation of the receiving device.
162. In combination with a receiving device, 80 a sheet-feeding device comprising pneumatically-controlled drop and feed roller mechanism controlled by the advancing sheet, and further controlling means for said drop and feed roller to permit the coöperation of the 85 same only during the required space of time for delivering the sheet to the receiving device.
163. In combination with a receiving device, a sheet-feeding device comprising pneumati- 90 cally-controlled drop and feed roller mechanism controlled by the advancing sheet, and further controlling means for said drop and feed roller to permit the coöperation of the same only at the required moment in the cycle 95 of operation of the receiving device and during the required space of time for delivering the sheet to the receiving device.
164. In combination with a receiving device, a sheet-feeding device comprising a feed- 100 roller, a drop-roller for coöperating therewith, mounted on an oscillating member, and pneumatically-controlled latching means for said member.
165. In combination with a receiving device, 105 a sheet-feeding device comprising a feed-roller, a drop-roller for coöperating therewith, mounted on an oscillating member, pneumatically-controlled latching means for said member, and a valve-trip operated by 110 the advancing sheet for controlling the pneumatic means.
166. In combination with a receiving device, a sheet-feeding device comprising a feed- 115 roller, a drop-roller for coöperating therewith, mounted on an oscillating member, pneumatically-operated means controlled by the advancing sheet for controlling said member, and a cam operated in unison with the receiving device for the further control of the 120 oscillating member.
167. In combination with a receiving device, a sheet-feeding device comprising a feed- 125 roller, a drop-roller for coöperating therewith, mounted on an oscillating member, pneumatically-operated means controlled by the advancing sheet for controlling said member, and a cam operated in unison with the

receiving device for the further control of the oscillating member to permit the coöperation of the drop and feed roller.

168. In combination with a receiving device, 5 a sheet-feeding device comprising a feed-roller, a drop-roller for coöperating therewith, mounted on an oscillating member, pneumatically-operated means controlled by the advancing sheet for controlling said member, a wheel 10 on said oscillating member and a cam operated in unison with the receiving device coöperating with said wheel for the further control of the oscillating member, said cam provided with a peripheral recess, the extent of 15 which has relation to the duration of coöperation between the drop and feed rollers.

169. In combination with a receiving device, 20 a sheet-feeding device comprising a feed-roller, a drop-roller for coöperating therewith, mounted on an oscillating member, pneumatically-operated means controlled by the advancing sheet for controlling said member, a wheel 25 on said oscillating member and a cam operated in unison with the receiving device coöperating with said wheel for the further control of the oscillating member, said cam provided with a peripheral recess the position and 30 extent of which have relation to the moment and duration of coöperation between the drop and feed rollers.

170. In combination with a receiving device, 35 a sheet-feeding device comprising a feed-roller, a drop-roller for coöperating therewith, mounted on an oscillating member, pneumatically-controlled latching means for said member, and a cam operated in unison with the receiving device for further controlling the operation 40 of the oscillating member.

171. In combination with a receiving device, 40 a sheet-feeding device comprising a feed-roller, a drop-roller for coöperating therewith, mounted on an oscillating member, pneumatically-controlled latching means for said member, a valve-trip operated by the advancing 45 sheet for controlling the pneumatic means, and a cam operated in unison with the receiving device for further controlling the operation of the oscillating member.

172. In combination with a receiving device, 50 a sheet-feeding device comprising a feed-roller, a drop-roller for coöperating therewith, mounted on an oscillating member, pneumatically-controlled latching means for said member, and a cam operated in unison with the receiving device for actuating the oscillating member to cause the separation of the drop and feed rollers during a required space of time.

173. In combination with a receiving device, 60 a sheet-feeding device comprising a feed-roller, a drop-roller for coöperating therewith, mounted on an oscillating member, pneumatically-controlled latching means for said member, and a cam operated in unison with the re-

ceiving device for actuating the oscillating member having a peripheral depression the 65 location of which is relative to the required moment of coöperation of the drop and feed rollers.

174. In combination with a receiving device, 70 a sheet-feeding device comprising a feed-roller, a drop-roller for coöperating therewith, mounted on an oscillating member, pneumatically-controlled latching means for said member, and a cam operated in unison with the receiving device for actuating the oscillating member, having a peripheral depression 75 the position and extent of which are relative to the moment and duration of the required coöperation of the drop and feed rollers.

175. In combination with a receiving device, 80 a sheet-feeding device comprising a feed-roller, a drop-roller for coöperating therewith, mounted on an oscillating member, pneumatically-controlled latching means for said member, a valve-trip operated by the advancing 85 sheet for controlling the pneumatic means, and a cam operated in unison with the receiving device for controlling the operation of the oscillating member.

176. In combination with a receiving device, 90 a sheet-feeding device comprising a feed-roller, a drop-roller for coöperating therewith, mounted on an oscillating member, pneumatically-controlled latching means for said member, a valve-trip operated by the advancing 95 sheet for controlling the pneumatic means, and a cam operated in unison with the receiving device for the further control of the oscillating member, having a peripheral depression 100 the position of which is relative to the required moment of coöperation of the drop and feed rollers.

177. In combination with a receiving device, 105 a sheet-feeding device comprising a feed-roller, a drop-roller for coöperating therewith, mounted on an oscillating member, pneumatically-controlled latching means for said member, a valve-trip operated by the advancing 110 sheet for controlling the pneumatic means, and a cam operated in unison with the receiving device for the further control of the oscillating member, having a peripheral depression 115 the extent of which has relation to the required duration of coöperation between the drop and feed rollers.

178. In combination with a receiving device, 120 a sheet-feeding device comprising a feed-roller, a drop-roller for coöperating therewith, mounted on an oscillating member, pneumatically-controlled latching means for said member, a valve-trip operated by the advancing 125 sheet for controlling the pneumatic means, and a cam operated in unison with the receiving device for the further control of the oscillating member, having a peripheral depression the position and extent of which have

relation to the required moment and duration of coöperation between the drop and feed rollers.

179. In combination with a receiving device, 5 a sheet - feeding device comprising a feed-roller, a drop-roller for coöperating therewith mounted on a spring - controlled oscillating member and pneumatically-controlled latching means for said member.

180. In combination with a receiving device, a sheet - feeding device comprising a feed-roller, a drop-roller for coöperating therewith, mounted on a spring - controlled oscillating member, pneumatically - controlled latching 15 means for said member, and a valve-trip operated by the advancing sheet for controlling the pneumatic means.

181. In combination with a receiving device, 20 a sheet - feeding device comprising a feed-roller, a drop-roller for coöperating therewith mounted on a spring - controlled oscillating member, a rocking shaft for supporting said member, a cam operated in unison with the receiving device for actuating the rocking 25 shaft, and latching means controlled by the advancing sheet for the further control of the oscillating member.

182. In combination with a receiving device, 30 a sheet - feeding device comprising a feed-roller, a drop-roller for coöperating therewith, mounted on a spring - controlled oscillating member, a rocking-shaft for supporting said member, a cam operated in unison with the receiving device for actuating the rocking shaft 35 and spring means connected between the rocking shaft and the oscillating member.

183. In combination with a receiving device, 40 a sheet - feeding device comprising a feed-roller, a drop-roller for coöperating therewith, mounted on a spring - controlled oscillating member, a rocking shaft for supporting said member which is loosely mounted thereon and a cam operated in unison with the receiving device for actuating the rocking shaft.

184. In combination with a receiving device, 45 a sheet - feeding device comprising a feed-roller, a drop-roller for coöperating therewith, mounted on a spring - controlled oscillating member, a rocking shaft for supporting said 50 member which is loosely mounted thereon, a cam operated in unison with the receiving device for actuating the rocking shaft and spring means connected between the rocking shaft and the oscillating member.

185. In combination with a receiving device, 55 a sheet - feeding device comprising a feed-roller, a drop-roller for coöperating therewith, mounted on a spring - controlled oscillating member, pneumatically - controlled latching 60 means for said member, and a cam operated in unison with the receiving device for further controlling the operation of the oscillating member.

186. In combination with a receiving device, 65 a sheet - feeding device comprising a feed-

roller, a drop-roller for coöperating therewith, mounted on a spring - controlled oscillating member, pneumatically - controlled latching means for said member, a valve-trip operated by the advancing sheet for controlling the 70 pneumatic means, and a cam operated in unison with the receiving device for further controlling the operation of the oscillating member.

187. In combination with a receiving device, 75 a sheet - feeding device comprising a feed-roller, a drop-roller for coöperating therewith, mounted on a spring - controlled oscillating member, a rocking shaft for supporting said member, a cam operated in unison with the 80 receiving device for actuating the rocking member and pneumatically - controlled latching means for controlling said actuation.

188. In combination with a receiving device, 85 a sheet - feeding device comprising a feed-roller, a drop-roller for coöperating therewith, mounted on a spring - controlled oscillating member, a rocking shaft for said oscillating member which is loosely mounted thereon, a spring connected between the shaft and member, a cam operated in unison with the receiving device for actuating the shaft and pneumatically-controlled latching means for controlling said actuation.

189. In combination with a receiving device, 90 a sheet - feeding device comprising a feed-roller, a drop-roller for coöperating therewith, mounted on a spring - controlled oscillating member, a rocking shaft for said oscillating member which is loosely mounted thereon, adjustable spring means connected between the 95 shaft and member, a cam operated in unison with the receiving device for actuating the shaft and pneumatically - controlled latching means for controlling said actuation.

190. In combination with a receiving device, 100 a sheet - feeding device comprising a feed-roller, a drop-roller for coöperating therewith, mounted on a spring - controlled oscillating member, a rocking shaft for supporting said 105 oscillating member, a cam operated in unison with the receiving device for actuating the rocking shaft, a valve-controlled latch for said oscillating member and a trip for said valve controlled by the advancing sheet.

191. In combination with a receiving device, 110 a sheet - feeding device comprising a feed-roller, a drop-roller for coöperating therewith, mounted on a spring - controlled oscillating member, a rocking shaft for said member 115 which is loosely mounted thereon, a cam operated in unison with the receiving device for actuating the shaft, pneumatically-controlled latching means for controlling said actuation and a valve-trip operated by the advancing sheet for controlling the pneumatic means.

192. In combination with a receiving device, 120 a sheet - feeding device comprising a feed-roller, a drop-roller for coöperating therewith, mounted on a spring - controlled oscillating 130

- member, a rocking shaft for said member which is loosely mounted thereon, a spring connected between said shaft and member, a cam operated in unison with the receiving device for actuating the shaft, pneumatically-controlled latching means for controlling said actuation and a valve-trip operated by the advancing sheet for controlling the pneumatic means.
193. In combination with a receiving device, a sheet-feeding device comprising a feed-roller, a drop-roller for coöperating therewith, mounted on a spring-controlled oscillating member, a rocking shaft for said member, an adjustable spring means operating between said shaft and member, a cam operated in unison with the receiving device for actuating the shaft, pneumatically-controlled latching means for controlling said actuation and a valve-trip operated by the advancing sheet for controlling the pneumatic means.
194. In a sheet-feeding machine, the combination of a drop and feed roller mechanism comprising an idler normally out of engagement with the feed-roller, a supporting member for said idler and a cam-controlled member having spring connection with the supporting member.
195. In a sheet-feeding machine, the combination of a drop and feed roller mechanism comprising an idler normally out of engagement with the feed-roller, a supporting member for said idler, and a cam-controlled member, having spring connection with the supporting member, both members mounted on a common shaft.
196. In a sheet-feeding machine, the combination of a drop and feed roller mechanism comprising an idler normally out of engagement with the feed-roller, a supporting member for said idler and a cam-controlled member having adjustable spring connection with the supporting member.
197. In a sheet-feeding machine, the combination of a drop and feed roller mechanism comprising an idler normally out of engagement with the feed-roller, a supporting member for said idler, a cam-controlled member having adjustable spring connection with the supporting member, both members mounted on a common shaft.
198. In a sheet-feeding machine, the combination of a drop and feed roller mechanism comprising an idler normally out of engagement with the feed-roller, a supporting member for said idler, and a spring-pressed cam-controlled member having spring connection with the supporting member.
199. In a sheet-feeding machine, the combination of a drop and feed roller mechanism comprising an idler normally out of engagement with the feed roller, a supporting member for said idler, a spring-pressed cam-controlled member having spring connection with the supporting member, both members mount- 65 ed on a common shaft.
200. In a sheet-feeding machine, the combination of a drop and feed roller mechanism comprising an idler normally out of engagement with the feed-roller, a supporting member for said idler and a spring-pressed cam-controlled member having adjustable spring connection with the supporting member.
201. In a sheet-feeding machine, the combination of a drop and feed roller mechanism comprising an idler normally out of engagement with the feed-roller, a supporting member for said idler, a spring-pressed cam-controlled member having adjustable spring connection with the supporting member, both members mounted on a common shaft.
202. In a sheet-feeding machine, the combination of a drop and feed roller mechanism comprising an idler normally out of engagement with the feed-roller, a supporting member for said idler, a cam-controlled member having spring connection with the supporting member, and pneumatically-operated latching means for the cam-controlled member.
203. In a sheet-feeding machine, the combination of a drop and feed roller mechanism comprising an idler normally out of engagement with the feed-roller, a supporting member for said idler, a cam-controlled member, both members loosely mounted on a common shaft, and pneumatically-operated latching means for the cam-controlled member.
204. In a sheet-feeding machine, the combination of a drop and feed roller mechanism comprising an idler normally out of engagement with the feed-roller, a supporting member for said idler, a cam-controlled member having adjustable spring connection with the supporting member, and pneumatically-operated latching means for the cam-controlled member.
205. In a sheet-feeding machine, the combination of a drop and feed roller mechanism comprising an idler normally out of engagement with the feed-roller, a supporting member for said idler, a cam-controlled member having adjustable spring connection with the supporting member, both members loosely mounted on a common shaft, and pneumatically-operated latching means for the cam-controlled member.
206. In a sheet-feeding machine, the combination of a drop and feed roller mechanism comprising an idler, a supporting member for said idler, a spring-pressed cam-controlled member having spring connection with the supporting member, and pneumatically-operated latching means for the cam-controlled member.
207. In a sheet-feeding machine, the combination of a drop and feed roller mechanism comprising an idler normally out of engagement with the feed-roller, a supporting mem-

ber for said idler, a spring-pressed cam-controlled member, both members loosely mounted on a common shaft, and pneumatically-operated latching means for the cam-controlled member.

208. In a sheet-feeding machine, the combination of a drop and feed roller mechanism comprising an idler normally out of engagement with the feed-roller, a supporting member for said idler, a spring-pressed cam-controlled member having adjustable spring connection with the supporting member, and pneumatically-operated latching means for the cam-controlled member.

209. In a sheet-feeding machine, the combination of a drop and feed mechanism comprising an idler normally out of engagement with the feed-roller, a supporting member for said idler, a spring-pressed cam-controlled member having adjustable spring connection with the supporting member, both members loosely mounted on a common shaft, and pneumatically-operated latching means for the cam-controlled member.

210. In a sheet-feeding machine, the combination of a drop and feed roller mechanism comprising an idler normally out of engagement with the feed-roller, an oscillating supporting member for said idler, a cam for controlling said oscillating member, latching means for the further control of said oscillating member and pneumatically-operated mechanism for controlling the latching means, said latching means being so constructed as to respond to the pneumatically-controlled mechanism only when the same is operated simultaneously with or prior to the arrival into the operative position of the cam.

211. In a sheet-feeding machine, the combination of a drop and feed roller mechanism comprising an idler normally out of engagement with the feed-roller, an oscillating supporting member for said idler, a cam for controlling said oscillating member, latching means for the further control of said oscillating member and pneumatically-operated mechanism for controlling the latching means and a detent in said latching means for restraining the same during certain positions of the cam.

212. In a sheet-feeding machine, the combination of a drop and feed roller mechanism comprising an idler normally out of engagement with the feed-roller, an oscillating member for supporting the idler, a cam for controlling the movement of the oscillating member, and latching means for the further control of the oscillating member having a detent for restraining the operation of said latching means.

213. In a sheet-feeding machine, the combination of a drop and feed roller mechanism comprising an idler normally out of engagement with the feed-roller, an oscillating member for supporting the idler, a cam for controlling the oscillating member, latching means

for the further control of the oscillating member and pneumatically-controlled mechanism for operating the latching means, said latching means being provided with coöperating beveled faces so disposed as to permit the operation of the same at the required moment of operation of the cam.

214. In a sheet-feeding machine, the combination of a drop and feed roller mechanism comprising an idler normally out of engagement with the feed-roller, a spring-pressed cam-controlled oscillating member for supporting the idler and spring-pressed pneumatically-controlled latching means for said oscillating member adapted to operate only at the required moment of operation of the cam.

215. In combination with a receiving device, a sheet-feeding machine comprising a feed-roller, and a drop-roller for coöperating therewith mounted on a spring-controlled oscillating member, a cam operated in unison with the receiving device for controlling the oscillating member to permit the coöperation of the drop and feed roller during a required space of time and pneumatically-controlled latching means so arranged as to be operated only at the moment of operation of the cam which will permit the maximum cam-controlled coöperation of said drop and feed roller.

216. In combination with a receiving device, a sheet-feeding machine comprising a feed-roller, a drop-roller for coöperating therewith mounted on an oscillating member, a cam member operated in unison with the receiving device for controlling the operation of the oscillating member having a depression of sufficient extension to permit the coöperation of the drop and feed rollers during a required space of time, pneumatically-controlled latching means for the further control of said oscillating member, the members of said latching means being so constructed as to be released from each other only when actuated by the pneumatically-operated mechanism contemporaneously or prior to the arrival into the operating position of the depression in the cam.

217. In combination with a receiving device, a sheet-feeding machine comprising a feed-roller, a drop-roller for coöperating therewith mounted on an oscillating member, a cam operated in unison with a receiving device for controlling the operation of the oscillating member, means for combing the sheets toward the drop and feed roller, means for moving the combing means into and out of engagement with the sheets, latching means for the further control of said oscillating member, and a detent in said latching means controlled by the cam.

218. In combination with a receiving device, a sheet-feeding machine comprising a feed-roller, a drop-roller for coöperating therewith mounted on an oscillating member, a cam

operated in unison with a receiving device for controlling the operation of the oscillating member, means for combing the sheets toward the drop and feed roller, pneumatically-operated means for moving the combing means into and out of engagement with the sheets and latching means controlled by the mechanism controlling the last-mentioned means for the further control of said oscillating member.

219. In combination with a receiving device, a sheet-feeding machine comprising a feed-roller, a drop-roller for coöperating therewith mounted on an oscillating member, a cam operated in unison with the receiving device for controlling the operation of the oscillating member, means for combing the sheets toward the drop and feed roller, pneumatically-operated means for moving the combing means into and out of engagement with the sheets, latching means controlled by the mechanism controlling the last-mentioned means for the further control of said oscillating member, and a valve-trip operated by the advancing sheet for controlling the pneumatically-operated means.

220. In a sheet-feeding machine, the combination of coöperating drop and feed rollers, a bifurcated, oscillating supporting member for the drop-roller and a fixed supporting member for the feed-roller, said supporting members serving as guides for the sheet as it advances therebetween.

221. In a sheet-feeding machine, the combination of coöperating drop and feed rollers, pneumatic means for controlling the operation of the same, a valve-trip for controlling the pneumatic means and a supporting member for the feed-roller provided with recesses for receiving the lower extensions of the valve-trip.

222. In a sheet-feeding machine the combination of coöperating drop and feed rollers, a bifurcated supporting member for the drop-roller provided with horizontally-extending guide-fingers.

223. In a sheet-feeding machine, the combination of coöperating drop and feed rollers, a double-bifurcated supporting member having the drop-roller located between the inner two prongs of same and a valve-trip for controlling the operation of said supporting member having its arm extending between the two inner and the two prongs of said supporting member.

224. In a sheet-feeding machine, the combination of coöperating drop and feed rollers, a supporting member for the drop-roller loosely mounted on a supporting-shaft, a coupling member adjustably connected between said supporting member and the stationary parts of the machine for preventing lateral movement but permitting rotative movement of said supporting member on the shaft.

225. In a sheet-feeding machine, the combi-

nation of coöperating drop and feed rollers, a supporting member for the drop-roller loosely mounted on a rocking shaft, a boss keyed to the shaft to limit the independent rotative but to permit a lateral movement between the supporting member and said shaft.

226. In a sheet-feeding machine, the combination of coöperating drop and feed rollers, a supporting member for the drop-roller loosely mounted on a supporting-shaft, a boss keyed to the shaft to prevent rotative but to permit lateral movement of the supporting member on said shaft, and a coupling member adjustably connected between said supporting member and the stationary parts of the machine for preventing lateral movement but permitting rotative movement of said supporting member on the shaft.

227. In a sheet-feeding machine, the combination of a drop and feed roller, a supporting member for the drop-roller loosely mounted on a rocking shaft, means carried upon and adjustably connected with said shaft for limiting the independent rotative movement of said supporting member with respect to said shaft.

228. In a sheet-feeding machine, the combination of a drop and feed roller loosely mounted on the supporting-shaft, spring means adjustably connected with said shaft for limiting the rotative movement of said supporting member.

229. In a sheet-feeding machine, the combination of a drop and feed roller, a supporting member for the drop-roller loosely mounted on the supporting-shaft, a member adjustably connected with said shaft having adjustable spring connection with the supporting member for controlling the rotative movement, but permitting free lateral movement of said member on said shaft.

230. In a sheet-feeding machine, the combination of a drop and feed roller, a supporting member for the drop-roller loosely mounted on the supporting-shaft, means adjustably connected with said shaft for limiting the rotative movement of said supporting member, and means adjustably connected between the stationary framework of the machine and said supporting member for preventing lateral movement but permitting rotative movement of said member on the shaft.

231. In a sheet-feeding machine, the combination of a drop and feed roller loosely mounted on the supporting-shaft, spring means adjustably connected with said shaft for limiting the rotative movement of said supporting member, and means adjustably connected between the stationary framework of the machine and said supporting member for preventing lateral movement but permitting rotative movement of said member on the shaft.

232. In a sheet-feeding machine, the combination of a drop and feed roller, a supporting member for the drop-roller loosely mounted on

- a supporting-shaft, a member adjustably connected with said shaft having adjustable spring connection with the supporting member for controlling the rotative movement, but permitting free lateral movement of said member on said shaft, and means adjustably connected between the stationary framework of the machine and said supporting member for preventing lateral movement but permitting rotative movement of said member on the shaft. 5
233. In a sheet-feeding machine, the combination of a drop and feed roller, a bifurcated supporting member for the drop-roller loosely mounted on the shaft, a boss mounted on said shaft between the branches of the bifurcated member, rotatably rigid with the shaft but laterally adjustable thereon and an adjustable spring connection between the boss and the bifurcated member. 15
234. In a presser-foot mechanism for sheet-feeding machines, the combination of a rocking shaft and means for operating the same, a presser-foot member, and sector-gear mechanism one element of which is operated by the rocking shaft, the other being spring-connected with the presser-foot as means for communicating motion from the rocking shaft to the presser-foot member. 20
235. In a presser-foot mechanism for sheet-feeding machines, the combination of a rocking shaft and means for operating the same, a presser-foot member, a shaft for supporting the same and sector-gear mechanism one element of which is operated by the rocking shaft, the other being spring-connected with the presser-foot-supporting shaft as means for communicating motion from the rocking shaft to the presser-foot member. 30
236. In a presser-foot mechanism for sheet-feeding machines, the combination of a rocking shaft and means for operating the same, a presser-foot member and a shaft for supporting the same and spring-controlled sector-gear mechanism one element of which is operated by the rocking shaft, the other element having spring connection with the presser-foot-supporting shaft as means for communicating motion from the rocking shaft to the presser-foot member. 40
237. In a presser-foot mechanism for sheet-feeding machines, the combination of a rocking shaft and means for operating the same, a presser-foot member and a shaft for supporting the same, a sector-gear one element of which is operated by the rocking shaft while the other element controls the presser-foot by spring-connected mechanism as means for communicating motion from the rocking shaft to the presser-foot member. 50
238. In a presser-foot mechanism for sheet-feeding machines, the combination of a rocking shaft and means for operating the same, a presser-foot member and a shaft for supporting the same and sector-gear mechanism, one element of which is operated by the rocking shaft, while the other element operates, through resilient means, the presser-foot as means for communicating motion from the rocking shaft to the presser-foot member. 60
239. A rotative shaft and means for operating the same, a projecting arm rotatably rigid therewith, a presser-foot member and a supporting-shaft rotatably rigid therewith, a second arm rotatably rigid with said shaft and an intermediate arm loosely mounted on said shaft being spring-connected with the last-mentioned arm and having sector-gear cooperation with the arm of the first-mentioned shaft. 70
240. In a presser-foot mechanism for sheet-feeding machines, the combination of a rocking shaft, an arm rotatably rigid therewith, a second arm pivotally secured to the free end of the first arm and extending horizontally from said pivotal connection and having a horizontal axis of movement and a presser-foot member secured to the free end of said second arm. 80
241. In a presser-foot mechanism for sheet-feeding machines, the combination of a rocking shaft, an arm rotatably rigid therewith, a second arm pivotally secured to the free end of said first arm having a substantially horizontal extension to the rear thereof and at an angle therewith and having a horizontal axis of movement and a presser-foot member secured to the free end of the second arm. 90
242. In a presser-foot mechanism for sheet-feeding machines, the combination of a rocking shaft, an arm rotatably rigid therewith, a second arm pivotally secured to the free end of said first arm having a substantially horizontal extension to the rear thereof and in the direction of the axis of its pivotal connection and a presser-foot member secured to the free end of said second arm. 100
243. In a presser-foot mechanism for sheet-feeding machines, the combination of a rocking shaft, an arm rotatably rigid therewith, a second arm pivotally secured to the free end of the first arm and extending horizontally from said pivotal connection and having a horizontal axis of movement and a presser-foot member adjustably secured to the free end of said second arm. 110
244. In a presser-foot mechanism for sheet-feeding machines, the combination of a rocking shaft, an arm rotatably rigid therewith, a second arm pivotally secured to the free end of said first arm having a substantially horizontal extension to the rear of said first arm and in the direction of the axis of said pivotal connection and a presser-foot member adjustably secured to the free end of said second arm. 120
245. In a presser-foot mechanism for sheet-feeding machines, the combination of a rocking shaft, an arm rotatable therewith having a bifurcated free end, a second arm pivotally secured to said bifurcated free end having a 130

substantially horizontal extension to the rear thereof and in the direction of the axis of its pivotal connection and a presser-foot member secured to the free end of said second arm.

5 246. In a presser-foot mechanism for sheet-feeding machines, the combination of a rocking shaft, an arm rotatably rigid therewith having a bifurcated free end, a second arm pivotally secured to said bifurcated free end

10 and having a substantially horizontal extension to the rear of said first arm and in the direction of the axis of said pivotal connection and a presser-foot member adjustably secured to the free end of said second arm.

15 247. In a presser-foot mechanism for sheet-feeding machines, the combination of a rocking shaft, an arm rotatably rigid therewith, a second arm pivotally secured to the free end of the first arm and extending horizontally

20 from said pivotal connection, said pivotal connection having a horizontal axis, and a presser-foot member having a vertical extension secured in the free end of said second arm.

25 248. In a presser-foot mechanism for sheet-feeding machines, the combination of a rocking shaft, an arm rotatably rigid therewith, a second arm pivotally secured to the free end of said first arm having a substantially horizontal extension to the rear thereof and in the

30 direction of the axis of its pivotal connection and a presser-foot member having a vertical extension secured to the free end of said second arm.

35 249. In a presser-foot mechanism for sheet-feeding machines, the combination of a rocking shaft, an arm rotatably rigid therewith, a second arm pivotally secured to the free end of the first arm and extending horizontally from said pivotal connection and a presser-

40 foot member having a vertical extension at right angles with the axis of said pivotal connection adjustably secured to the free end of said second arm:

45 250. In a presser-foot mechanism for sheet-feeding machines, the combination of a rocking shaft, an arm rotatably rigid therewith, a second arm pivotally secured to the free end of said first arm having a substantially horizontal extension to the rear of said first arm

50 and in the direction of the axis of said pivotal connection and a presser-foot member having a vertical extension adjustably secured to the free end of said second arm.

55 251. In a presser-foot mechanism for sheet-feeding machines, the combination of a rocking shaft, an arm rotatably rigid therewith having a bifurcated free end, a second arm pivotally secured to said free end and extending horizontally from its pivotal connection

60 and a presser-foot member having a vertical extension at right angles with the axis of said pivotal connection secured to the free end of said second arm.

65 252. In a presser-foot mechanism for sheet-feeding machines, the combination of a rock-

ing shaft, an arm rotatable therewith having a bifurcated free end, a second arm pivotally secured to said bifurcated free end having a substantially horizontal extension to the rear thereof and in the direction of the axis of its 70 pivotal connection and a presser-foot member having a vertical extension secured to the free end of said second arm.

75 253. In a presser-foot mechanism for sheet-feeding machines, the combination of a rocking shaft, an arm rotatably rigid therewith having a bifurcated free end, a second arm pivotally secured to said bifurcated free end and extending horizontally from said pivotal connection and a presser-foot member having 80 a vertical extension at right angles with the axis of said pivotal connection adjustably secured to the free end of said second arm.

85 254. In a presser-foot mechanism for sheet-feeding machines, the combination of a rocking shaft, an arm rotatably rigid therewith having a bifurcated free end, a second arm pivotally secured to said bifurcated free end and having a substantially horizontal extension to the rear of said first arm and in the 90 direction of the axis of said pivotal connection and a presser-foot member having a vertical extension adjustably secured to the free end of said second arm.

95 255. In a presser-foot mechanism for sheet-feeding machines, the combination of a rocking shaft, an arm rotatably rigid therewith, a second arm pivotally secured to the free end of the first arm and extending horizontally from said pivotal connection and a presser- 100 foot member having a horizontal extension and a vertical extension at right angles with the axis of said pivotal connection, the vertical extension secured to the free end of the second arm.

105 256. In a presser-foot mechanism for sheet-feeding machines, the combination of a rocking shaft, an arm rotatably rigid therewith, a second arm pivotally secured to the free end of the first arm and extending horizontally from said pivotal connection and a presser-foot member having a horizontal extension and a vertical extension at right angles with the axis of said pivotal connection, the vertical extension adjustably secured to the free 110 end of the second arm.

115 257. In a presser-foot mechanism for sheet-feeding machines, the combination of a rocking shaft, an arm rotatably rigid therewith, a second arm pivotally secured to the free end of the first arm and extending horizontally from said pivotal connection and having a horizontal axis of movement, and a presser-foot member having a threaded vertical extension and a horizontal extension, the vertical extension adjustably secured to the free end of the second arm and the horizontal extension provided at its free end with a contact-toe.

120 258. In a sheet-feeding machine, the combination with table-raising mechanism comprising 125

ing a pawl and ratchet, the pawl provided with a tripping-lug, a reciprocative member for engaging said lug as means for tripping said pawl to normally render it inoperative, and latching means controlled by the pile of sheets for controlling the tripping means.

259. In a sheet-feeding machine, the combination with table-raising mechanism comprising a pawl and ratchet, the pawl provided with a tripping-lug, a reciprocating trip to engage said lug for normally rendering the pawl inoperative, and latching means controlled by the pile of sheets for controlling the tripping means.

15 260. In a sheet-feeding machine, the combination with table-raising mechanism including a coöperative pawl and ratchet, the pawl provided with a tripping-lug, means for oscillating the pawl, means connected with the last-mentioned means for normally engaging said lug to trip the pawl, and latching means controlled by the pile of sheets for controlling the tripping means.

25 261. In a sheet-feeding machine, the combination with table-raising mechanism comprising a coöperating pawl and ratchet, means for oscillating the pawl, tripping means connected with the oscillating means to engage said pawl for normally holding it out of engagement with the ratchet, and latching means controlled by the pile of sheets for controlling the tripping means.

35 262. In a sheet-feeding machine, the combination of table-raising mechanism including a coöperating pawl and ratchet, means for oscillating the pawl, cam-operated pawl-trip for normally preventing the coöperation of the pawl and ratchet and latching means controlled by the pile of sheets for restraining the cam-operated trip.

45 263. In a sheet-feeding machine, the combination of table-raising mechanism including a coöperating pawl and ratchet, means for oscillating the pawl, a cam-operated pawl-trip for normally preventing the coöperation of the pawl and ratchet, latching means for restraining the cam-operated trip and a presser-foot operated by the pile of sheets for operating the latching means.

55 264. In a sheet-feeding machine, the combination of table-raising mechanism comprising a pawl and ratchet and an elevating-screw operated thereby, the pawl provided with a tripping-lug, a trip for engaging said lug to control the operation of the pawl and latching means controlled by the pile of sheets for controlling the trip.

60 265. In a sheet-feeding machine, the combination of table-raising mechanism comprising a coöperating pawl and ratchet and an elevating-screw operated thereby, means for oscillating the pawl, a trip oscillated by the oscillating means for normally engaging said pawl to prevent its coöperation with the ratchet,

and latching means controlled by the pile of sheets for controlling the trip.

266. In a sheet-feeding machine, the combination of table-raising mechanism including a coöperative pawl and ratchet and an elevating-screw operated thereby, means for oscillating the pawl, tripping means connected with the oscillating means for normally disengaging said pawl from the ratchet and latching means controlled by the pile of sheets for controlling the tripping means.

75 267. In a sheet-feeding machine, the combination of table-raising mechanism including a coöperating pawl and ratchet and an elevating-screw operated thereby, means for oscillating the pawl, cam-operated pawl-trip for normally preventing the coöperation of the pawl and ratchet and pawl-trip-latching means controlled by the pile of sheets.

80 268. In a sheet-feeding machine, the combination of table-raising mechanism including a coöperating pawl and ratchet and an elevating-screw operated thereby, means for oscillating the pawl, cam-operated pawl-trip for normally preventing the coöperation of the pawl and ratchet, pawl-trip-latching means and a presser-foot operated by the pile of sheets for operating the latching means.

85 269. In a sheet-feeding machine, the combination of table-raising mechanism comprising an elevating-screw, pawl-and-ratchet means for operating the screw, the pawl provided with a tripping-lug, a driven shaft for operating the pawl-and-ratchet means, tripping means for engaging the said lug to render the pawl inoperative and latching means controlled by the pile of sheets for controlling the tripping means.

90 270. In a sheet-feeding machine, the combination of table-raising mechanism comprising an elevating-screw and pawl-and-ratchet means for operating the same, a driven shaft for operating the pawl-and-ratchet means, controlling mechanism operated by the driven shaft for tripping the pawl and thereby rendering inactive the pawl-and-ratchet means, and latching means operated by the pile of sheets for restraining said controlling mechanism.

95 271. In a sheet-feeding machine, the combination of table-raising mechanism comprising an elevating-screw and pawl-and-ratchet means for operating the same, a driven shaft for operating the pawl-and-ratchet means, controlling mechanism operated by the driven shaft for tripping the pawl and thereby rendering inactive the pawl-and-ratchet means, and latching means for restraining said controlling mechanism, a presser-foot operated by the pile of sheets for operating the latching means.

100 272. In a sheet-feeding machine, the combination of table-raising mechanism, comprising a pawl and ratchet, the pawl provided with a

tripping-lug, tripping means operated by a rocking member for engaging said lug to render said pawl inoperative and latching means controlled by the pile of sheets for controlling the rocking member.

273. In a sheet-feeding machine, the combination of table-raising mechanism comprising a pawl and ratchet, the pawl provided with a tripping-lug, tripping means operated by a spring-controlled rocking member for engaging said lug to render said pawl inoperative, and latching means controlled by the pile of sheets for controlling the spring-controlled rocking member.

274. In a sheet-feeding machine, the combination of table-raising mechanism, comprising a pawl-and-ratchet means, a rotating shaft for operating said means, pawl-tripping means normally operated by the rotating shaft for rendering the pawl-and-ratchet means inoperative and latching means controlled by the pile of sheets for restraining the tripping means.

275. In a sheet-feeding machine, the combination of table-raising mechanism, comprising a pawl-and-ratchet means, a rotating shaft for operating said means, pawl-tripping means normally operated by the rotating shaft for rendering the pawl-and-ratchet means inoperative, latching means for restraining the tripping means and a presser-foot controlled by the pile of sheets for operating the latching means.

276. In a sheet-feeding machine, the combination of table-raising mechanism, comprising a pawl-and-ratchet means, a rotating shaft for operating said means, cam-operated pawl-tripping means normally operated by the rotating shaft for rendering the pawl - and - ratchet means inoperative and latching means controlled by the pile of sheets for restraining the tripping means.

277. In a sheet-feeding machine, the combination of table-raising mechanism, comprising a pawl-and-ratchet means, a rotating shaft for operating said means, cam-operated pawl-tripping means normally operated by the rotating shaft for rendering the pawl - and - ratchet means inoperative, latching means for restraining the tripping means and a presser-foot controlled by the pile of sheets for operating through spring tension the latching means.

278. In a sheet-feeding machine, the combination of table-raising mechanism comprising pawl - and - ratchet means and an elevating-screw operated thereby, pawl-tripping means for rendering said pawl and ratchet inoperative, and spring - controlled latching means controlled by the pile of sheets for controlling the tripping means.

279. In a sheet-feeding machine, the combination of table-raising mechanism comprising a pawl and ratchet and an elevating-screw operated thereby, pawl-tripping means for ren-

dering said pawl and ratchet inoperative, latching means for controlling the tripping means and a presser-foot operated by the pile of sheets for controlling through spring tension the latching means.

280. In a sheet-feeding machine, the combination of table-raising mechanism, comprising a pawl-and-ratchet means and an elevating-screw operated thereby, a rotating shaft for operating said means, pawl-tripping means normally operated by the rotating shaft for rendering the pawl-and-ratchet means inoperative and latching means controlled through spring tension by the pile of sheets for restraining the tripping means.

281. In a sheet-feeding machine, the combination of table-raising mechanism, comprising pawl - and - ratchet means and an elevating-screw operated thereby, a rotating shaft for operating said means, pawl-tripping means normally operated by the rotating shaft for rendering the pawl-and-ratchet means inoperative, latching means for restraining the tripping means and a presser-foot controlled by the pile of sheets for operating through spring tension the latching means.

282. In a sheet-feeding machine, the combination of table-raising mechanism, comprising a pawl-and-ratchet means and an elevating-screw operated thereby, a rotating shaft for operating said means, cam - operated pawl-tripping means normally operated by the rotating shaft for rendering the pawl-and-ratchet means inoperative and latching means controlled through spring tension by the pile of sheets for restraining the tripping means.

283. In a sheet-feeding machine, the combination of table-raising mechanism, comprising pawl - and - ratchet means and an elevating-screw operated thereby, a rotating shaft for operating said means, cam - operated pawl-tripping means normally operated by the rotating shaft for rendering the pawl-and-ratchet means inoperative, latching means for restraining the tripping means and a presser-foot controlled by the pile of sheets for operating through spring tension the latching means.

284. In a sheet-feeding machine, the combination of table-raising mechanism, comprising pawl-and-ratchet means, a rotating shaft for operating said means, pawl-tripping means for rendering the pawl-and-ratchet means inoperative, a cam rotated in unison with the rotating shaft for operating the tripping means and latching means operated through spring tension by the pile of sheets for restraining the operation of the tripping means.

285. In a sheet-feeding machine, the combination of table-raising mechanism comprising a pawl and ratchet, a driven shaft for operating said pawl and ratchet, a cam rotating in unison with the shaft, a pawl-trip operated thereby for normally rendering the pawl and ratchet inoperative, and latching means con-

trolled through spring tension by the pile of sheets for controlling the cam-operated means.

286. In a sheet-feeding machine, the combination of table-raising mechanism comprising 5 a pawl and ratchet, a driven shaft for operating said pawl, and ratchet, a cam rotating in unison with the shaft a pawl-trip operated thereby for normally rendering the pawl and ratchet inoperative, latching means controlled by the pile of sheets for controlling the cam-operated means and a presser-foot controlled by the pile of sheets for controlling through spring tension the latching means.

287. In a sheet-feeding machine, the combination of table-raising mechanism, comprising 15 pawl-and-ratchet means and an elevating-screw operated thereby, a rotating shaft for operating said means, pawl-tripping means for rendering the pawl-and-ratchet means inoperative, a cam rotated in unison with the rotating shaft for operating the tripping means and latching means operated through spring tension by the pile of sheets for restraining the operation of the tripping means.

288. In a sheet-feeding machine, the combination of table-raising mechanism comprising a pawl and ratchet and an elevating-screw operated thereby, a driven shaft for operating said pawl and ratchet, a cam rotating in unison with the shaft and a pawl-trip operated thereby for normally rendering the pawl and ratchet inoperative, latching means controlled through spring tension by the pile of sheets for controlling the cam-operated means.

289. In a sheet-feeding machine, the combination of table-raising mechanism comprising a pawl and ratchet and an elevating-screw operated thereby, a driven shaft for operating said pawl and ratchet, a cam rotating in unison with the shaft, a pawl-trip operated thereby for normally rendering the pawl and ratchet inoperative, latching means for controlling the cam-operated pawl-trip and a presser-foot controlled by the pile of sheets for controlling 45 through spring tension the latching means.

290. In a sheet-feeding machine, the combination of table-raising mechanism comprising a pawl-and-ratchet-operated screw mechanism, and a rotatable member having the same 50 axis of movement as that of the pawl, adapted to be arbitrarily operated for rendering said pawl inoperative.

291. In a sheet-feeding machine, the combination of table-raising mechanism comprising 55 a pawl and ratchet, a stud for supporting the pawl, a member on the stud having a projection for encountering the pawl and a spring connected with said member for maintaining it in one of two alternative rotative positions.

292. In a sheet-feeding machine, the combination of table-raising mechanism comprising a pawl and ratchet, a stud for supporting the pawl, a member on the stud having a projection for encountering the pawl and a spring 65 connected with said member for maintaining

it in one of two alternative rotative positions and also for locking said member and pawl against lateral movement on said stud.

293. In a sheet-feeding machine, the combination of table-raising mechanism comprising 70 an elevating-screw and pawl-and-ratchet means for rotating same, a reciprocating trip for rendering the pawl inactive, automatic means controlled by the pile of sheets for controlling the trip and a manually-operative 75 member for arbitrarily operating said screw.

294. In a sheet-feeding machine, the combination of table-raising mechanism comprising 80 an elevating-screw and pawl-and-ratchet means for rotating same, a reciprocating trip 85 for rendering the pawl inactive, automatic means controlled by the pile of sheets for controlling the trip and a manually-operative pinion geared with the screw-operating mechanism for arbitrarily rotating said screw.

295. In a sheet-feeding machine, the combination of table-raising mechanism comprising a screw either to elevate or lower said table and pawl-and-ratchet means for rotating the screw a reciprocating trip for rendering the 90 pawl inactive, automatic means controlled by the pile of sheets for controlling the trip and a manually-operative pinion geared with the screw-operating mechanism for arbitrarily rotating said screw.

296. In a sheet-feeding machine, the combination of table-raising mechanism comprising 95 an elevating-screw and pawl-and-ratchet means for causing the rotation of same, means for operating said pawl and ratchet, reciprocating pawl-tripping means connected with the operating means for rendering the pawl 100 inoperative, latching means for controlling the tripping means and manually-operative means for arbitrarily operating the elevating-screw 105 independently of the pawl and ratchet.

297. In a sheet-feeding machine, the combination of combing means, pneumatic means controlled by the advancing sheet for automatically disengaging the combing means from 110 the sheets, and manually-operated means for arbitrarily disengaging the combing means from the sheets.

298. In a sheet-feeding machine, the combination of combing means, automatic means 115 controlled by the advancing sheet for disengaging the combing means from the sheets and manually-operated means for arbitrarily disengaging the combing means independently of the automatic means.

299. In a sheet-feeding machine, the combination of combing means, pneumatic means controlled by the advancing sheet for automatically disengaging the combing means from the sheets, and manually-operated cam 120 and roller means for arbitrarily disengaging the combing means from the sheets.

300. In a sheet-feeding machine, the combination of combing means, automatic means controlled by the advancing sheet for disen- 125

130

gaging the combing means from the sheets, and manually-operated cam and roller means for arbitrarily disengaging the combing means independently of the automatic means.

5 301. In a sheet-feeding machine, the combination of combing means, pneumatic means controlled by the advancing sheet for automatically disengaging the combing means from the sheets, a manually-operated recessed 10 cam and mechanism connected therewith for arbitrarily disengaging the combing means from the sheets and maintaining said disengagement.

15 302. In a sheet-feeding machine, the combination of combing means, automatic means controlled by the advancing sheet for disengaging the combing means from the sheets, a manually-operated recessed cam and mechanism connected therewith for arbitrarily dis- 20 engaging the combing means from the sheets and maintaining said disengagement.

25 303. In a sheet-feeding machine, the combination of a combing-wheel, a bearing therefor, raising and lowering mechanism connected with said bearing and means connected with said mechanism for indicating the height of the pile of sheets.

30 304. In a sheet-feeding machine, the combination of a combing-wheel, a pivoted bracket carrying a supporting-stud for said wheel, raising and lowering mechanism for said supporting-stud and a connecting-rod between said mechanism and the supporting-stud having graduations thereon for indicating the 35 height of the pile of sheets.

35 305. In a sheet-feeding machine, the combination of a combing-wheel, a pivoted bracket carrying a supporting-stud for said wheel, raising and lowering mechanism, means for 40 connecting the same with the supporting-stud and means connected therewith for indicating the height of the pile of sheets.

45 306. In a sheet-feeding machine, the combination of means for generating air-pressure, a conducting system connected therewith, pneumatically-operated combing mechanism connected with said system and discharge-nozzles also connected with said system for directing currents of air between the edges of the sheets.

50 307. In a sheet-feeding machine, the combination of means for generating air-pressure, a conducting system connected therewith, pneumatically-operated mechanism connected with said system and an automatic valve in said 55 system controlled by the advancing sheet.

60 308. In a sheet-feeding machine, the combination of means for generating air-pressure, a conducting system connected therewith, pneumatically-operated combing mechanism connected with said system, discharge - nozzles connected with said system for directing currents of air between the edges of the sheets, and means for the vertical, longitudinal and rotative adjustment of said discharge-nozzles.

65 309. In a sheet-feeding machine, the combi-

nation of means for generating air-pressure, a conducting system connected therewith, pneumatically-operated mechanism connected with said system, an automatic valve in said system controlled by the advancing sheet, and discharge-nozzles also connected with said system for directing currents of air between the edge of the sheets.

70 310. In a sheet-feeding machine, the combination of means for generating air-pressure, a conducting system connected therewith, pneumatically-operated mechanism connected with said system, an automatic valve in said system controlled by the advancing sheet, discharge-nozzles also connected with said system for directing currents of air between the edge of the sheets and means for the vertical, longitudinal and rotative adjustment of said discharge-nozzles.

75 80 311. In a sheet-feeding machine, the combination of means for generating air-pressure, a conducting system connected therewith, pneumatically - operative mechanism connected with said system and adjustable pressure-regulating air-reservoir means connected with said system.

85 312. In a sheet-feeding machine, the combination of means for generating air-pressure, a conducting system connected therewith, pneumatically - operative mechanism connection 90 with said system and spring-controlled pressure-regulating air-reservoir means connected with said system.

90 313. In a sheet-feeding machine, the combination of means for generating air-pressure, a conducting system connected therewith, pneumatically - operative mechanism connected with said system and adjustable spring-controlled pressure - regulating air - reservoir means connected with said system.

100 105 314. In a sheet-feeding machine, the combination of means for generating air-pressure, a conducting system connected therewith, pneumatically - operated mechanism connected with said system, discharge-nozzles also connected with said system for directing currents of air between the edges of the sheets and adjustable spring - controlled pressure - regulating air-reservoir means connected with said system.

110 115 315. In a sheet-feeding machine, the combination of means for generating air-pressure, a conducting system connected therewith, pneumatically - operated mechanism connected with said system, an automatic valve in said system controlled by the advancing sheet, and adjustable spring - controlled pressure - regulating air-reservoir means connected with said system.

120 125 316. In a sheet-feeding machine, the combination of means for generating air-pressure, a conducting system connected therewith, discharge-nozzles connected with said system for directing currents of air between the edges of the sheets, means for the vertical, longitu- 130

nal and rotative adjustment of said discharge-nozzles and adjustable spring-controlled pressure-regulating air-reservoir means connected with said system.

5 317. In a sheet-feeding machine, the combination of means for generating air-pressure, a conducting system connected therewith, pneumatically-operated mechanism connected with said system, an automatic valve in said system controlled by the advancing sheet, discharge-nozzles also connected with said system for directing currents of air between the edge of the sheets and adjustable spring-controlled pressure-regulating air-reservoir means connected with said system.

10 318. In a sheet-feeding machine, the combination of means for generating air-pressure, a conducting system connected therewith, pneumatically-operated mechanism connected with said system, an automatic valve in said system controlled by the advancing sheet, discharge-nozzles also connected with said system for directing currents of air between the edge of the sheets, means for the vertical, longitudinal and rotative adjustment of said discharge-nozzles and adjustable spring-controlled pressure-regulating air-reservoir means connected with said system.

15 319. In a sheet-feeding machine, the combination of means for moving the sheets forwardly, a plurality of feed-guides having horizontal extensions for supporting the under side of the sheets and means for the horizontal adjustment of some of said guides with respect to the others.

20 320. In a sheet-feeding machine, the combination of pneumatically-controlled means for moving the sheets forwardly, a plurality of feed-guides having horizontal extensions above the forward end of the sheet, a supporting-shaft therefor and laterally-adjustable means for detachably securing the said feed-guides on the shaft.

25 321. In a sheet-feeding machine, the combination of a plurality of coöperating feed-guides having horizontal extensions above and below the front edge of the sheet, supporting-shafts for said guides and detachable means for securing the lateral adjustment of said guides on said shafts.

30 322. In a sheet-feeding machine, the combination of guide means for the edges of the pile of sheets comprising a shaft, a supporting-arm adjustably secured thereto and a vertically-disposed member supported by said supporting-arm and having a free vertical movement with respect thereto.

35 323. In a sheet-feeding machine, the combination of a plurality of coöperating feed-guides having horizontal extensions above and below the front edge of the sheet, supporting-shafts for said guides and detachable means for securing the lateral adjustment of said guides on said shafts and a vertically-slidable

side guide having means for limiting its downward movement.

324. In a sheet-feeding machine, the combination of a pair of horizontal supporting-shafts, a plurality of vertically-disposed piling-guides secured thereto, each having independent lateral adjustment thereon and means for the simultaneous horizontal movement of said shafts.

40 325. In a sheet-feeding machine, the combination of a pair of horizontal supporting-shafts, a plurality of vertically-disposed piling-guides secured thereto, each having independent lateral adjustment thereon and rack-and-pinion means for the simultaneous horizontal movement of said shafts.

45 326. In a sheet-feeding machine, the combination of a plurality of vertically-extending piling-guides, a pair of horizontal supporting-shafts therefor, said shafts provided with pinions, supporting-racks coöperating with said pinions and means for rotating said shafts to secure the simultaneous forward-and-backward movement of same.

50 327. In a sheet-feeding machine, the combination of a plurality of vertically-extending piling-guides, a pair of horizontal supporting-shafts therefor, said shafts provided with pinions connected by a pair of interposed idlers for securing the simultaneous horizontal movement of said two shafts, racks coöperating with said pinions and means for rotating said shafts to cause a forward-and-backward movement of same.

55 328. In a sheet-feeding machine, the combination of a plurality of vertically-extending piling-guides, a pair of horizontal supporting-shafts therefor, said shafts provided with pinions connected by a pair of interposed idlers, racks coöperating with said pinions and means for rotating said shafts to cause a forward-and-backward movement of same.

60 329. In a sheet-feeding machine, the combination of horizontally-extending under feed-guides, a pair of horizontal supporting-shafts, a plurality of vertically-disposed piling-guides secured to said shafts, provided with horizontal extensions at their upper ends for coöperation with said feed-guides, each having independent lateral adjustment thereon and means for the simultaneous horizontal movement of said shafts.

65 330. In a sheet-feeding machine, the combination of a pair of horizontal supporting-shafts, a plurality of front piling-guides having lateral adjustment thereon, a side piling-guide having a vertical extension to the rear of the vertical extensions of the front piling-guides, also having lateral adjustment on the supporting-shafts and manually-operated mechanism for the simultaneous forward-and-backward movement of said supporting-shafts.

70 331. In a sheet-feeding machine, the combination of a pair of horizontal supporting-shafts, a plurality of front piling-guides having lateral adjustment thereon, a side piling-guide having a vertical extension to the rear of the vertical extensions of the front piling-guides, also having lateral adjustment on the supporting-shafts and manually-operated mechanism for the simultaneous forward-and-backward movement of said supporting-shafts.

nation of a pair of horizontal supporting-shafts one vertically above the other, a plurality of front piling-guides having lateral adjustment thereon, a vertically-extending side piling-guide to the rear of the front piling-guides also having lateral adjustment on the supporting-shafts and manually-operative rack-and-pinion mechanism for the simultaneous forward-and-backward movement of said supporting-shafts.

332. In a sheet-feeding machine, the combination of horizontally-extending under feed-guides, a plurality of vertically-disposed piling-guides provided with horizontal extensions at their upper ends for coöperation with said feed-guides, a pair of horizontal supporting-shafts, the piling-guides each having independent lateral adjustment thereon and means for the simultaneous horizontal movement of said shafts.

333. In a sheet-feeding machine, the combination of horizontally-extending upper feed-guides, a pair of horizontal supporting-shafts, a plurality of vertically-disposed front piling-guides having independent lateral adjustment on said shafts, provided with horizontal extensions at their upper ends for coöperation with said feed-guides, and means for the simultaneous horizontal movement of said shafts.

334. In a sheet-feeding machine, the combination of horizontally-extending under and upper feed-guides, a pair of horizontal supporting-shafts, a plurality of vertically-disposed piling-guides, each having independent lateral adjustment on said shafts, and provided with horizontal extensions at their upper ends for coöperation with said feed-guides, and means for the simultaneous horizontal movement of said shafts.

335. In a sheet-feeding machine, the combination of a table, means for moving the table in either of two directions, the one transverse of the other, and flange-and-channel means for the slidable engagement between the said moving means.

336. In a sheet-feeding machine, the combination of a table, rack-and-pinion means for its horizontal movement in one direction, screw means for its horizontal transverse movement, and channel-and-flange means for the slidable engagement between the said moving means.

337. In a sheet-feeding machine, the combination of a table, and adjustable means therefor comprising screw means for altitudinal adjustment, and a pinion connected with the table and a coöperating channeled rack member for horizontal adjustment.

338. In a sheet-feeding machine, the combination of a table, manually-operative rack-and-pinion and screw means for its two-way horizontal adjustment and channel-and-flange means for the slidable engagement between the said rack-and-pinion and screw means.

339. In a sheet-feeding machine, the combi-

nation of a table, rack-and-pinion means for its horizontal adjustment in one direction, screw means for its horizontal adjustment in a transverse direction, and channel-and-flange means for the engagement between said rack-and-pinion and screw-operated means to permit the independent operation of one with respect to the other.

340. In a sheet-feeding machine, the combination of a table, means for its altitudinal adjustment, rack-and-pinion means for its horizontal adjustment in one direction, screw means for its horizontal transverse adjustment, and channel-and-flange means for the slidable engagement between the rack-and-pinion and screw means.

341. In a sheet-feeding machine, the combination of a table, means for its altitudinal adjustment, manually-operative rack-and-pinion means for its horizontal movement, manually-operative screw means for horizontal transverse movement, and channel-and-flange means for the slidable engagement of the rack-and-pinion means with the screw means.

342. In a sheet-feeding machine, the combination of a table, manually-operative means for its horizontal movement in one direction, screw means for its horizontal transverse movement, a flange connected with the rack means, and a channel provided in connection with the screw means for coöperating with the flange.

343. In a sheet-feeding machine, the combination of a table, a frame for supporting said table, screw means for supporting said frame, adapted to vary its altitudinal adjustment and means provided between the table and the frame for securing the horizontal adjustment of said table in two directions one transverse of the other, said means comprising slotted flanged members adapted to slide upon horizontal portions of the frame and angle-irons secured to the table and adapted to rest in the slots of said flanged members upon said horizontal portion of the frame and means for arbitrarily shifting the flanged members along the frame and means for arbitrarily shifting the angle-irons in a direction transverse the direction of movement of said flanged members.

344. In a sheet-feeding machine, the combination of a table, a frame for supporting the same, screw means for supporting the frame and for varying its altitudinal adjustment and manually-operative means for the horizontal adjustment of the table on the frame comprising a screw-actuated rack member having horizontal slidable engagement with the frame, and a pinion member secured to the table for coöperating with the rack member, causing its movement in a direction approximately at right angles with the direction of movement of the screw-actuated rack member.

345. In a sheet-feeding machine, the combination of a table, a frame for supporting the same, screw means for supporting the frame

and for varying its altitudinal adjustment and manually-operative means for the horizontal adjustment of the table on the frame comprising a screw-actuated rack member 5 having horizontal slidable engagement with the frame, and a pinion - actuated member coöperating with the rack member, secured to the table for causing its movement in a direction approximately at right angles with the 10 direction of movement of the screw-actuated rack member.

346. In a sheet-feeding machine, the combination of a table for the sheets, a frame for supporting the table, screw means for supporting the frame and varying its altitudinal adjustment and means, secured between the table and the frame, for the horizontal adjustment of said table in directions one at right angles with the other, said means comprising 15 screw-actuated members slidably mounted on said frame and transverse members secured to the table adapted to engage with said screw-actuated members and to slide upon said frame approximately at right angles to the direction 20 of movement of the screw-actuated members.

347. In a sheet-feeding machine, the combination of a table for the sheets, a frame for supporting the table, screw means for supporting the frame and varying its altitudinal 30 adjustment and means, secured between the table and the frame, for the horizontal adjustment of said table in directions one at right angles with the other, said means comprising screw-actuated members slidably mounted on 35 said frame and transverse members secured to the table adapted to engage with said screw-actuated members and to slide upon said frame approximately at right angles to the direction 40 of movement of the screw-actuated members, and rack-and-pinion means for actuating the transverse members.

348. In a sheet-feeding machine, the combination of a table for the sheets, a frame for supporting the table, screw means for supporting the frame and varying its altitudinal 45 adjustment, and means, secured between the table and the frame, for the horizontal adjustment of said table in directions one at right angles with the other, said means comprising 50 slotted screw - actuated members slidably mounted on said frame and transverse members secured to the table engaging the slots of the slotted members and movable on the frame approximately at right angles with the direction 55 of the movement of the slotted members.

349. In a sheet-feeding machine, the combination of a table, a plurality of vertical supporting-screws for varying the altitudinal adjustment of the same and means connected 60 between the table and the screw for permitting tilting movement of the table with respect to the screws.

350. In a sheet-feeding machine, the combination of a table, means for varying the altitudinal adjustment of the same comprising

supporting-screws, and threaded sleeves for coöperation therewith, and means intermediate the table and the sleeves for permitting tilting movement of the table with respect to the screws.

351. In a sheet-feeding machine the combination of a table, means for varying the altitudinal adjustment of the same comprising vertical screws, and threaded sleeves for coöperation therewith, and means intermediate 70 the table and the sleeves for permitting tilting movement of the table with respect to the screws.

352. In a sheet-feeding machine, the combination of a table, a supporting-frame therefor, supporting-screws for varying the altitudinal adjustment of the frame and means intermediate the frame and screws for permitting the tilting movement of the frame with respect to the screws.

353. In a sheet-feeding machine, the combination of a table, a plurality of supporting-screws for varying the altitudinal adjustment of the same, a rotative shaft and coöperative gears acting between the shaft and screws for 80 actuating the screws and means for rendering a gear inoperative.

354. In a sheet-feeding machine, the combination of a table, supporting-screws for varying the altitude of same, means for normally actuating said screws simultaneously, and means for arbitrarily rendering inactive certain of 90 said screws to secure the required tilting adjustment of the table.

355. In a sheet-feeding machine, the combination of a table, a pair of vertical screws coöperating therewith for the altitudinal adjustment of the same, a manually-operative shaft and coöperating gears between the shaft and screws for actuating the screws simultaneously 100 and spring-controlled means for rendering inactive a gear.

356. In a sheet-feeding machine, the combination of a table, a pair of vertical screws coöperating therewith for the altitudinal adjustment of the same, a manually - operative 110 shaft and coöperating gears between the shaft and screws for actuating the screws simultaneously and manually-operative means for rendering inactive a gear.

357. In a sheet-feeding machine, the combination of a table, a pair of vertical screws coöperating therewith for the altitudinal adjustment of the same, a manually - operative shaft and coöperating gears between the shaft 120 and screws for actuating the screws simultaneously and spring-controlled means for rendering inactive a gear to permit the operation of one screw independently of the other.

358. In a sheet-feeding machine, the combination of a table, a pair of vertical screws coöperating therewith for the altitudinal adjustment of the same, a manually-operative shaft and coöperating gears between the shaft and screws for actuating the screws simultaneously 130

ously and manually-operative means for rendering inactive a gear to permit the operation of one screw independently of the other.

359. In a sheet-feeding machine, the combination of a table, a pair of supporting-screws for varying its altitudinal adjustment, an operating-shaft having gear connection with said screws and manually-operative means for releasing a gear from its fixed connection with the shaft so that it may rotate freely thereon.

360. In a sheet-feeding machine, the combination of a table, a pair of supporting-screws for varying its altitudinal adjustment, manually-operative means for actuating said screws and means for arbitrarily disengaging the operative relationship between the actuating means and one of said screws.

361. In a sheet-feeding machine, the combination of a table, a pair of supporting-screws for varying its altitudinal adjustment, means connected between the table and the screws for permitting tilting movement with respect to the screws, manually-operative means for actuating said screws and means for arbitrarily disengaging the operative relationship between the actuating means and one of said screws.

362. In a sheet-feeding machine, the combination of pneumatically-operated mechanism, a valve-trip mechanism for controlling the same, a common supporting structure for said associated mechanism having adjustable connection with the stationary framework of the machine.

363. In a sheet-feeding machine, the combination of pneumatically-operated mechanism, a valve-trip mechanism for controlling the same, a common supporting structure for said associated mechanism having adjustable connection with the stationary framework of the machine, and manually-operative means for shifting the position of said supporting structure with respect to said stationary framework.

364. In a sheet-feeding machine, the combination of pneumatically-operated mechanism, a valve-trip mechanism for controlling the same, a common supporting structure for said associated mechanism connected with the stationary framework of the machine, and manually-operative rack-and-pinion means for the lateral adjustment of said supporting structure on said stationary framework.

365. In a sheet-feeding machine, the combination of combing means, pneumatically-controlled mechanism for raising and lowering the same, a valve-trip for controlling said mechanism and a common supporting structure for all the above-recited elements having adjustable connection with the stationary parts of the machine.

366. In a sheet-feeding machine, the combination of combing means, a drop-roller, pneumatically-controlled mechanism for raising and lowering the same, a valve-trip for con-

trolling said mechanism and a common supporting structure for all the above-recited elements having adjustable connection with the stationary parts of the machine.

367. In a sheet-feeding machine, the combination of combing means, a drop-roller, a presser-foot, pneumatically-controlled mechanism for raising and lowering the same, a valve-trip for controlling said mechanism and a common supporting structure for all the above-recited elements having adjustable connection with the stationary parts of the machine.

368. In a sheet-feeding machine, the combination of combing means, pneumatically-controlled mechanism for raising and lowering the same, a valve-trip for controlling said mechanism and a common supporting structure for all the above-recited elements connected with the stationary parts of the machine, and rack-and-pinion means for the lateral adjustment of said common supporting structure.

369. In a sheet-feeding machine, the combination of combing means, a drop-roller, pneumatically-controlled mechanism for raising and lowering the same, a valve-trip for controlling said mechanism and a common supporting structure for all the above-recited elements connected with the stationary parts of the machine, and rack-and-pinion means for the lateral adjustment of said common supporting structure.

370. In a sheet-feeding machine, the combination of combing means, a drop-roller, a presser-foot, pneumatically-controlled mechanism for raising and lowering the same, a valve-trip for controlling said mechanism and a common supporting structure for all the above-recited elements connected with the stationary parts of the machine, and rack-and-pinion means for the lateral adjustment of said common supporting structure.

371. In a sheet-feeding machine, the combination of combing means, pneumatically-controlled mechanism for raising and lowering the same, a valve-trip for controlling said mechanism and a common supporting structure for all the above-recited elements having adjustable connection with the stationary parts of the machine and clamping means for maintaining said adjustment.

372. In a sheet-feeding machine, the combination of combing means, pneumatically-controlled mechanism for raising and lowering the same, a valve-trip for controlling said mechanism and a common supporting structure for all the above-recited elements connected with the stationary parts of the machine, rack-and-pinion means for the lateral adjustment of said common supporting structure, and clamping means for maintaining said adjustment.

373. In a sheet-feeding machine, the combination of a combing-wheel, pneumatically-op-

erated mechanism for raising and lowering the same, a supporting structure for said mechanism, and a combing-wheel-supporting frame having rotative connection with the supporting structure.

374. In a sheet-feeding machine, the combination of a combing-wheel, mechanism for raising and lowering the same, a valve-trip for controlling said mechanism, a supporting structure for said mechanism and valve-trip, and a supporting-frame for the combing-wheel having pivotal connection with said supporting structure.

375. In a sheet-feeding machine, the combination of a combing-wheel, mechanism for raising and lowering the same, a valve-trip for controlling said mechanism, a supporting structure for said mechanism and valve-trip, and a supporting-frame for the combing-wheel having pivotal connection with said supporting structure and connecting means between the free end of the combing-wheel frame and said raising and lowering mechanism.

376. In a sheet-feeding machine, the combination of a combing-wheel, pneumatically-operated mechanism for raising and lowering the same, a supporting structure for said mechanism adjustably secured to the stationary framework of the machine, and a combing-wheel-supporting frame having rotative connection with said supporting structure.

377. In a sheet-feeding machine, the combination of a combing-wheel, mechanism for raising and lowering the same, a valve-trip for controlling said mechanism, a supporting structure for said mechanism and valve-trip, adjustably secured to the stationary framework of the machine, and a supporting-frame for the combing-wheel having pivotal connection with said supporting structure.

378. In a sheet-feeding machine, the combination of a combing-wheel, mechanism for raising and lowering the same, a valve-trip for controlling said mechanism, a supporting structure for said mechanism and valve-trip, adjustably secured to the stationary framework of the machine, and a supporting-frame for the combing-wheel having pivotal connection with said supporting structure, and connecting means between the free end of the combing-wheel frame and said raising and lowering mechanism.

379. In a sheet-feeding machine, the combination of automatic mechanism for operating upon the sheets, a tripping member controlled by the advancing sheet for controlling the automatic mechanism, spring means for controlling the tripping member and means for shifting the direction of spring tension to hold the trip in the operative or inoperative position.

380. In a sheet-feeding machine, the combination of automatic mechanism for operating upon the sheets, a pivoted tripping member

controlled by the advancing sheet for controlling the automatic mechanism, spring means for controlling the tripping member and means for shifting the direction of spring tension from one side of the pivot center to the other.

381. In a sheet-feeding machine, the combination of automatic mechanism for operating upon the sheets, a pivoted tripping member controlled by the advancing sheet for controlling the automatic mechanism, spring means for controlling the tripping member and means for maintaining the line of spring tension upon one side or the other of the pivot as may be desired.

382. In a sheet-feeding machine, the combination of pneumatically-operated mechanism for operating upon the sheets, a valve-trip controlled by the advancing sheet for controlling the pneumatic mechanism, spring means for controlling the valve-trip, and means for shifting the direction of spring tension to hold the trip in the operative or inoperative position.

383. In a sheet-feeding machine, the combination of pneumatically-operated mechanism for operating upon the sheets, a pivoted valve-trip controlled by the advancing sheet for controlling the pneumatic mechanism, spring means for controlling the valve-trip and means for shifting the direction of spring tension from one side of the pivot center to the other.

384. In a sheet-feeding machine, the combination of pneumatically-operated mechanism for operating upon the sheets, a pivoted valve-trip controlled by the advancing sheet for controlling the pneumatic mechanism, spring means for controlling the valve-trip and means for maintaining the line of spring tension upon one side or the other of the pivot as may be desired.

385. In a sheet-feeding machine, the combination of automatic mechanism for operating upon the sheets, a pivoted trip controlled by the advancing sheet for controlling the automatic mechanism, a spring for actuating said trip and a projecting pivot-pin adapted to encounter the spring to prevent the same passing the center of said pivot.

386. In a sheet-feeding machine, the combination of automatic mechanism for operating upon the sheets, a pivoted trip controlled by the advancing sheet for controlling the automatic mechanism, spring means for controlling said trip and a projecting pivot-pin adapted to engage the spring when placed on one side thereof to hold the trip in the inoperative position.

387. In a sheet-feeding machine, the combination of pneumatically-operated mechanism for operating upon the sheets, a valve-trip controlled by the advancing sheet for controlling the pneumatic mechanism, spring means for controlling the valve-trip, means for shifting the direction of spring tension to hold the

trip in the operative or inoperative position, and adjustable means for varying the force of spring tension exerted upon said trip.

388. In a sheet-feeding machine, the combination of pneumatically-operated mechanism for operating upon the sheets, a pivoted valve-trip controlled by the advancing sheet for controlling the pneumatic mechanism, spring means for controlling the valve-trip, means for shifting the direction of spring tension from one side of the pivot center to the other, and adjustable means for varying the force of spring tension exerted upon said trip.

389. In a sheet-feeding machine, the combination of pneumatically-operated mechanism for operating upon the sheets, a pivoted valve-trip controlled by the advancing sheet for controlling the pneumatic mechanism, spring means for controlling the valve-trip, means for maintaining the line of spring tension upon one side or the other of the pivot as may be desired, and adjustable means for varying the force of spring tension exerted upon said trip.

390. In a sheet-feeding machine, the combination of automatic mechanism for operating upon the sheets, a pivoted trip controlled by the advancing sheet for controlling the automatic mechanism, a spring for actuating said trip, a projecting pivot-pin adapted to engage the spring to prevent the same passing the center of said pivot, and adjustable means for varying the force of spring tension exerted upon said trip.

391. In a sheet-feeding machine, the combination of automatic mechanism for operating upon the sheets, a pivoted trip controlled by the advancing sheet for controlling the automatic mechanism, spring means for controlling said trip, a projecting pivot-pin adapted to engage the spring when placed on one side thereof to hold the trip in the inoperative position, and adjustable means for varying the force of spring tension exerted upon said trip.

392. In a sheet-feeding machine, the combination of a single combing-wheel adapted to operate upon the sheet near one of its side margins, a guide member in substantial rear alinement with the combing-wheel for encountering the side edges of the sheets and a presser-weight slidable on the guide member for engaging the top of the sheet.

393. In a sheet-feeding machine, the combination of a single combing-wheel adapted to operate upon the sheet near one of its side margins, a vertically-disposed guide member in substantial alinement with the combing-wheel for encountering the side edges of the sheets and a presser-weight slidable on the guide member for engaging the top of the pile of sheets.

394. In a sheet-feeding machine, the combination of a single combing-wheel adapted to operate upon the sheet near one of its side margins, a side guide member in substantial rear alinement with the combing-wheel and a

presser-weight slidable on the guide member for engaging the top of the pile of sheets.

395. In a sheet-feeding machine, the combination of a single combing-wheel adapted to operate upon the sheet near one of its side margins, a guide member in substantial rear alinement with the combing-wheel for encountering the side edges of the sheets, a presser-weight slidable on the guide member for engaging the top of the sheet, and a presser-foot in substantial alinement, in the direction of sheet travel, with the combing-wheel and presser-weight.

396. In a sheet-feeding machine, the combination of a single combing-wheel adapted to operate upon the sheet near one of its side margins, a vertically-disposed guide member in substantial alinement with the combing-wheel for encountering the side edges of the sheets, a presser-weight slidable on the guide member for engaging the top of the pile of sheets, and a presser-foot in substantial alinement, in the direction of sheet travel, with the combing-wheel and presser-weight.

397. In a sheet-feeding machine, the combination of a single combing-wheel adapted to operate upon the sheet near one of its side margins, a side guide member in substantial rear alinement with the combing-wheel, a presser-weight slidable on the guide member for engaging the top of the pile of sheets, and a presser-foot in substantial alinement, in the direction of the sheet travel, with the combing-wheel and presser-weight.

398. In a sheet-feeding machine, the combination of a single combing-wheel adapted to operate upon the sheet near one of its side margins, a guide member in substantial rear alinement with the combing-wheel for encountering the side edges of the sheets, a presser-weight slidable on the guide member for engaging the top of the sheet, and a presser-foot to the rear of and in substantial alinement, in the direction of the sheet travel, with the combing-wheel and presser-weight.

399. In a sheet-feeding machine, the combination of a single combing-wheel adapted to operate upon the sheet near one of its side margins, a vertically-disposed guide member in substantial alinement with the combing-wheel for encountering the side edges of the sheets, a presser-weight slidable on the guide member for engaging the top of the pile of sheets, and a presser-foot to the rear of and in substantial alinement, in the direction of the sheet travel, with the combing-wheel and presser-weight.

400. In a sheet-feeding machine, the combination of a single combing-wheel adapted to operate upon the sheet near one of its side margins, a side guide member in substantial rear alinement with the combing-wheel, a presser-weight slidable on the guide member for engaging the top of the pile of sheets, and a presser-foot to the rear of and in substantial

alinement, in the direction of the sheet travel, with the combing-wheel and presser-weight.

401. In a sheet-feeding machine, the combination of a single combing-wheel, drop and

5 feed rollers, automatic means controlled by the advancing sheet for raising and lowering the combing-wheel and drop-rollers, the combing-wheel positioned to operate upon the sheet near the margin, guide and presser-weight

10 means, positioned to the rear of the combing-wheel, comprising a vertically - extending guide member adapted to bear against the edges of the sheets and a weight slidably mounted thereon for engaging the top of the

15 pile of sheets.

402. In a sheet-feeding machine, the combination of a single combing-wheel, drop and feed rollers and a presser - foot, automatic means, controlled by the advancing sheet, for

20 raising and lowering the combing-wheel, drop-rollers and presser-foot, the combing-wheel positioned to operate upon the sheet near its margin, guide and presser-weight means in rear alinement with the combing-wheel, the

25 guide engaging the side edges of the sheets, the presser-weight slidably mounted on said guide and engaging the top of the pile.

403. In a sheet-feeding machine, the combination of a single combing-wheel, drop and

30 feed rollers and a presser - foot, automatic means controlled by the advancing sheet for raising and lowering the combing-wheel, drop-rollers and presser-foot, the combing-wheel

alternating with rollers and presser-foot, the

35 combing-wheel positioned to operate upon the sheet near its side margin, guide and presser-weight means in substantial rear alinement

with the combing-wheel, the guide engaging the side edges of the sheets, the presser-weight slidably mounted on said guide and engaging the top of the pile of sheets.

404. In a sheet-feeding machine, the combination of a single combing-wheel, drop-rollers and a presser-foot, automatic means controlled by the advancing sheet for raising and lowering the combing - wheel, drop - rollers and presser-foot at the required relative moments, the combing-wheel positioned to operate upon the sheet near its margin, guide and presser-weight means in rear alinement with the combing-wheel; the guide engaging the side edges of the sheets, the presser - weight slidably mounted on said guide and engaging the top of the pile.

405. In a sheet-feeding machine, the combination of a single combing-wheel, drop and feed rollers and a presser - foot, automatic means, controlled by the advancing sheet, for raising and lowering the combing-wheel, drop-rollers and presser-foot at the required relative moments, the combing-wheel positioned to operate upon the sheet near its side margin, guide and presser-weight means in substantial rear alinement with the combing-wheel, the guide engaging the side edges of the sheets, the presser-weight slidably mounted on said guide and engaging the top of the pile of sheets, and the presser-foot in substantial rear alinement with the combing-wheel and presser-weight.

HOWARD K. KING.
